UNITED STATES PATENT OFFICE

VINCENT E. HEYWOOD AND RALPH D. HOAGLUND, OF WORCESTER, MASSACHUSETTS, ASSIGNEES TO UNITED STATES ENVELOPE COMPANY, OF SPRINGFIELD, MASSACHUSETTS, A CORPORATION OF MAINE

MACHINE FOR MAKING PAPER CUPS

Application filed March 28, 1928. Serial No. 265,388.

The present invention relates to a machine for making drinking cups and the like out of thin material, such as paper. According to the invention, rapid and efficient production of completely formed cups is automatically secured, each cup consisting of a wall portion, of tubular sleeve formation, within which is assembled a separate bottom portion, of disk formation, the two being united by a water tight seam.

The invention resides in certain novel combinations and arrangements of mechanical devices, by which successively fed flat paper blanks are formed into the tubular sleeves that constitute wall portions of the cups; by which the disks that form the cup bottoms are successively punched out from a moving web of paper and are then, in suitably timed relation, brought and held in registry with the sleeve-forming devices while a sleeve is being formed in surrounding relation to each such bottom disk; by which a water tight seam is formed between each sleeve portion and the bottom disk which it surrounds; by which each cup thus assembled has the material at its open end flanged over to provide a rounded edge that avoids cutting the lips of the user; and finally, by which each finished cup is discharged from the machine in nesting relation to previously discharged cups.

Other further features of the invention are set forth more fully hereinafter, reference being had to the accompanying drawings, in which:

Fig. 1 is a view in front elevation of a cup machine embodying our invention.

Fig. 48 is a fragmentary view illustrating the normal functioning of a detecting mechanism cooperating with the secondary turret.

Fig. 49 is a view showing the parts of Fig. 48 in a different position.

Fig. 50 is a view similar to Fig. 38 illustrating a modification in the manner of driving the main and secondary turrets.

Fig. 51 is a plan view of the parts shown in Fig. 50.

Fig. 52 is a view in side elevation of the parts shown in Fig. 51.

Like reference characters refer to like parts in the different figures.

Before proceeding with the detailed description of the various groups of mechanism entering into our machine, a general descrip-

tion of the mode of operation will be first outlined with reference to the general views of Figs. 1 and 2 and the diagrammatic views of Figs. 3 and 4. As shown in Fig. 3 a stack of blanks 1 is provided, the blanks 1 being shown in plan in Fig. 2 and being of such form as to provide a hollow frusto conical sleeve when wrapped, as hereinafter described. A vertically reciprocating gummed picker 2 having a motion commonly employed for the pickers of envelope machines is adapted to lift a blank 1 from the stack into engagement with a stripper plate 3 above the stack which is adapted to remove the blank 1 from the picker 2 and hold it by suction from falling back on the stack. When the blank 1 is lifted by the picker 2 gum is applied thereto as shown at 4 in the plan view of Fig. 4.

The stripper plate 3 holds the blank 1 while a horizontally reciprocating carriage 5 enters beneath it, see Fig. 2, which carriage removes the blank from the plate 3 and moves it along horizontal rails 6 to its first station indicated at A. At this station A the blank 1 dwells momentarily while it may be embossed by suitable instrumentalities if desired. The blank 1 is then moved to the next station B where it remains at rest and then is moved again by the carriage 5 to a third station C which may be best termed the sleeve forming or wrapping station.

The wrapping station C represents the first station of the blank with relation to a revolving turret 7 indicated by a dot and dash circle in Fig. 3, which turret 7 has fifteen other stations lettered D to R inclusive, but before further describing the course of the blank 1 and the various operations performed thereon while on the large turret 7, the relation of the mechanism for forming the bottom disks of the cups will be described. While a blank is advancing step by step from station A to station C, a web 8 of paper drawn from a suitable roll is being advanced in a plane perpendicular to the blanks 1 as supported on the rails 6. As the web 8 reaches a point immediately above the wrapping station C, a circular disk 9 is punched therefrom which disk 9 is formed and moved downwardly and arrives at station C simultaneously with the arrival of a flat gummed blank 1. After the bottom disk 9 is positioned at station C, the flat blank 1 is wrapped into a sleeve about the bottom disk 9 in the manner shown in Figs. 10 to 15 inclusive, whereupon the sleeve with the bottom disk 9 included therein is moved to the next turret station D.

The turret 7 has a step-by-step motion imparted thereto so that for each revolution of what will be hereinafter termed the power shaft 10, see Fig. 1, the turret 7 will be turned through an angle equal to the angular displacement between any two stations C to R inclusive. The blank carriage 5 is driven in

timed relation from the power shaft 10 so that a blank is delivered to the wrapping station C each time the turret 7 is turned through the distance between two stations. Further-
5 more a bottom disk 9 is cut and delivered to station C in timed relation to the arrival of a blank 1 at this station.

At station D the wrapped blank 1 with the bottom disk 9 initially positioned therein is held idle while at station E the disk 9 is finally positioned and the sleeve sized as shown in Fig. 22. Stations F, G, and H are spinning stations at which the bottom portion of the sleeve extending beyond the disk 9 is flanged over as shown in Figs. 30, 31 and 32, while at station I the flanged bottom of the cup is finally interlocked with the bottom disk 9, as shown in Fig. 33. At stations J and K the interlocked rim and bottom are expanded 20 as shown in Fig. 36 while at stations L to P inclusive the partially completed cup is allowed to dry.

At station Q the cup is transferred from the main turret 7 to a secondary turret 11 indicated by the smaller dot and dash circle in Fig. 3, so that beyond the transfer station Q there is a vacant station R on the main turret where a detector device determines whether or not a completed cup has been removed. In 30 the event that a cup has not been removed at the transfer station Q means are provided for automatically stopping the machine to prevent double wrapping at the station C.

The secondary turret 11 is driven in timed relation with the main turret as shown in Fig. 38, so that as the turret moves from station Q to station R, the partially completed cup is moved to a station S on the turret 11 where a rim is spun onto the open end of the 40 cup by the mechanism shown in Fig. 40. The completed cup is then moved to station T on the secondary turret 11 where it is ejected from the machine, open end first.

Referring now to Figs. 1, 2 and 5 the power shaft 10 is shown as being rotatably mounted in vertical frame members 12 carried on a base 13 and power from any suitable source is adapted to be transmitted to the shaft 10 by means of a pulley 14. When the machine is not operating, the pulley 14 runs loose on the shaft 10 and the pulley 14 may be operatively connected to the shaft 10 by means of the longitudinally shiftable clutch member 15. The clutch member 15 is actuated by means 50 of a bell crank lever 16 which may be turned in any suitable manner to shift the member 15 and so clutch the pulley 14 to the shaft 10. For purposes of illustration, we have shown the clutch lever 16 as being operated by means 60 of a rod 17 connected to a piston 18 operable in a cylinder 19. Further details of this particular form of control for the clutch will be hereinafter described.

The upright frame members 12 support a 65 horizontal table 20 above the shaft 10 and

this table supports a large pedestal bearing 21 for rotatably supporting the main turret 7. As best shown in Fig. 5 a circular flange portion 7a constituting the turret proper is rotatable with a sleeve portion 22 mounted within the bearing 21 and held from longitudinal movement therein by means of a thrust collar 23. The periphery of the flange portion 7a provides gear teeth 24 which are in mesh with the teeth on a driving gear 25 mounted on a short shaft 26 extending parallel to and above the main driving shaft 10.

As best shown in Fig. 6, the gear 25 and with it the turret 7 is adapted to have imparted thereto an intermittent rotative movement from the drive shaft 10 by means of a so-called Geneva motion which comprises a crank 27 mounted on the shaft 10 and carrying a roller 28 adapted to be received in slots 29 provided in a spider 30 rotatable with the gear 25 on the shaft 26. With this arrangement, it is obvious that with each revolution of the drive shaft 10 the crank 27 cooperating with a slot 29 will serve to turn the shaft 26 through one quarter of a revolution. This intermittent turning movement of the shaft 26 will be imparted to the turret 7 through the gear 25 and it will be noted that the number of teeth 25a on the gear 25, included in an angle of 90°, is equal to the number of teeth 24 on the turret 7 included between the center lines X—X and Y—Y of two adjacent turret stations designated C and R for example.

In other words, each revolution of the main drive shaft 10 is adapted to cause the turret 7 to be turned through the angular distance between two adjacent stations so that continued rotation of the shaft 10 causes a uniform step-by-step movement to be imparted to the turret. It is also well to note at this point that the complete movement of the turret through the angular distance between two stations occurs as the main drive shaft 10 is making only about one quarter of a revolution after which the turret remains stationary in its new position until the shaft 10 has completed the other three quarters of its revolution. Thus a harmonic motion is imparted to the turret 7 and following each movement of the turret there occurs a dwell which measured in time, is approximately three times the duration of a single movement of the turret.

The main turret

Referring now to Fig. 7 there is shown on a large scale a cooperating cup form and and clamp as carried by the turret 7 at the wrapping station C, and as these parts of the other turret stations are identical in construction only one pair need be described in detail. The turret flange 7a is provided near its outer periphery with a number of equally spaced openings 31, the center lines of which are separated by a distance equal to the angu-

lar displacement of the turret 7 for each revolution of the shaft 10. Each opening 31 receives the cylindrical reduced portion 32 of a frusto conical cup form 33, the con-
 tour of which approximates the shape of the cup which is to be formed thereon. The cup form 33 is rigidly secured to the flange 7a by any suitable means such as a bolt 34 and is provided with a central longitudinal opening 35 for loosely receiving a hollow spindle 36 longer than the form 33. The spindle 36 carries at its end a head 37 which in the position shown is held against the smaller end of the cup form 33 by a spring 38 surrounding the spindle between the form 33 and an enlarged portion 36a.

The cup form 33 has a passage 39 extending therethrough parallel to and above the central opening 35 and this passage 39 has branches 40 extending radially therefrom to the periphery of the cup form, the passages 40 lying in the plane of the vertical axis of the station C as shown in Fig. 8. The longitudinal passage 39 registers with a passage 41 extending through the turret flange 7a and as best shown in Fig. 5 the opening of this passage 41 at the rear of the flange 7a is in alignment with an orifice 42 provided in a suction nozzle 43. The nozzle 43 is carried by a plunger 44 slidably mounted in the pedestal 45 which is part of the turret bearing 21 and the plunger 44 provides a longitudinal passage 46 which is permanently connected to a suitable source of suction not shown in Fig. 5.

The suction plunger 44 is adapted to be reciprocated in the pedestal 45 by means of the engaged end of a lever 47 pivoted at 48 with its lower end providing a roller 49 held in engagement with the face of a cam 50 by a spring 51 acting on the end of the plunger 44. The cam 50 is mounted on the shaft 10 and provides a raised portion 50a which when engaged by the roller 49 holds the suction plunger 44 retracted as shown in Fig. 5. However, when the roller 49 passes off the raised portion 50a the spring 51 forces the plunger 44 towards the turret flange 7a thereby causing the nozzle opening 42 to register closely with the opening 41 leading into the interior of the cup form 33. The cam 50 is so designed that its raised portion 50a holds the suction plunger 44 retracted only while the crank 27 of the Geneva motion is turning the turret 7 through the angle between two adjacent stations. As soon as the turret comes to rest the suction nozzle 43 is applied to the cup form 33 at station C and this suction is applied throughout the whole time that the cup form 33 remains at rest, namely through approximately three quarters of a revolution of the main drive shaft 10.

Referring again to Fig. 7 each cup form 33 has associated therewith a top clamp 52

pivotedly mounted on a plunger 53 by means of a pin 54. The plunger 53 is carried in a sleeve 55 which in turn is slidable within a housing 56 secured to the turret flange 7a by means of brackets 57. The upper end of the sleeve 55 extends beyond the sleeve housing 56 and carries a roll 58 that is held in engagement with the periphery of a cam 59 by means of a spring 60 one end of which is anchored to the housing 56 while the other end is secured to a stud 61 projecting from the sleeve 55. The plunger 53 is maintained in an extended position within the sleeve 55 by means of a spring 62 surrounding the plunger 53 between the clamp 52 and the lower end of the sleeve 55, a pin 53a limiting the outward movement of the plunger 53. As shown, the clamp 52 is held away from the surface of the cup form 33 by the action of the spring 60, although turning of the cam 59 will cause the clamp 52 to yieldingly engage the cup form 33 as will now be described with reference to Figs. 1 and 5.

The cam 59 is carried on the same axis as the turret 7 by a sleeve 63 extending through the sleeve 22 which carries the turret flange 7a. The opposite end of this sleeve 63 has connected thereto the hub portion 64 of a lever 65 projecting radially from the turret axis as shown in Fig. 24. The lever 65 is connected by means of a rod 66 to a fork 67 the arms of which straddle the main drive shaft 10. The fork 67 carries a roll 68 mounted on a pin 69 the roll 68 bearing on the surface of a cam 70 mounted on the shaft 10. The cam 70 is concentric about the shaft 10 for the major portion of its periphery and provides a projection 70a which imparts a limited angular movement to the lever 65 for a portion of each revolution of the main shaft 10.

As best shown in Fig. 1 the cam 59 is concentric about the axis of rotation of the turret 7 for the major portion of its periphery and the main radius of the cam 59 is such that all of the clamp rollers 58 resting on this concentric portion of the cam 59 are thrust outwardly to maintain the corresponding clamps 52 in engagement with their cup forms. The cam 59, however, provides a depression 71 which in the position shown in Fig. 1 is adapted to receive three clamp rollers 58 corresponding to stations C, R and Q. With respect to these rollers 58 the corresponding springs 60 are adapted to hold the clamps 52 retracted and out of engagement with the corresponding cup forms 33, see Fig. 7. This cam 59 is shown diagrammatically in Fig. 3 which represents the condition of affairs at the beginning of the cycle of operations resulting in the wrapping of a cup blank 1 which has just been received at the station C simultaneously with the arrival of a cup form 33 at this station through the operation of the mechanism previously de-

scribed. In the following description of the subsequent operations on the blank 1 at the wrapping station C it should be borne in mind that the main turret 7 is stationary during these operations which occur in the dwell in the movement of the main turret for each revolution of the main shaft 10.

Formation of cup sleeve

10 Referring again to Fig. 7 which is an enlarged view of the mechanism at the wrapping station C, a bottom clamp 72 is mounted below the cup form 33, this lower clamp 72 being diametrically opposed to the top seam 15 clamp 52 as shown in Fig. 8. The clamp 72 is carried by a spindle 73 extending downwardly through a sleeve 74 and received in a fork 75 carrying a roller 76. The sleeve 74 is slidably received in a bushing 77 secured 20 in an opening 78 provided in the table 20, the sleeve 74 projecting above the bushing 77 to provide a pair of spaced arcuate formers 79. As best shown in Fig. 8 the inner curvature 25 of each former 79 is substantially the same as the curvature of the periphery of the cup form 33 immediately above the clamp 72.

The spindle 73 which carries the clamp 72 is yieldingly supported on the roller fork 75 by means of a spring 80 surrounding the 30 spindle 73 between the upper surface of the fork 75 and a collar 81 pinned to the spindle 73. The sleeve 74 is also slidable on the roller fork 75 for a limited movement although the motion of the fork 75 is adapted to be directly 35 imparted to the sleeve 74 through studs 82 projecting from the fork 75 and received in slots 83 provided in the sleeve 74. A second spring 84 surrounding the spring 80 extends between the upper end of the roller fork 75 40 and a washer 85 positioned on a shoulder 85a provided on the inner surface of the sleeve 74 whereby the studs 82 are maintained in engagement with the lower ends of the slots 83.

As best shown in Figs. 5 and 8 the roller 76 45 rests on the periphery of a cam 86 mounted on the main shaft 10, the parts occupying the position shown in Fig. 8 when the roller 76 is on the low point of the cam 86. This position of parts represents the start of the blank 50 wrapping operation when a cup form 33 has just come into position and a blank 1 has been positioned under the cup form 33 as shown in Fig. 10 by mechanism which will be hereinafter described. As the shaft 10 continues to rotate from this point the cam 86 55 raises the roller 76 and with it the spindle 73 through the thrust of the inner spring 80. This movement of the spindle 73 causes the lower clamp 72 to engage the lower surface 60 of the blank 1 and yieldingly clamp it against the bottom of the form 33, as shown in Fig. 11.

However, as the roller 76 continues to move upwardly after the lower clamp 72 has 65 clamped the blank 1 against the rigid form

33 the spindle 73 telescopes within the fork 75, while the roller 76 carries the sleeve 74 with the formers 79 into the position shown in Fig. 12, wherein the blank 1 is positively clamped around the lower half of the cup 70 form 33, the inner spring 80 yielding to permit telescoping of the spindle 73. After reaching this point, the roll 76 remains in engagement with a concentric portion of the cam 86 thereby holding the formers 79 in 75 clamping position for the remainder of the wrapping operation, at the end of which the shaft 10 has completed its revolution and the roller 76 again engages the low point on cam 86 to return the parts to the position 80 shown in Fig. 10.

The right-hand former 79 has pivoted thereto a pair of levers 87 carrying at their free ends a cross shaft 88 on which is mounted a pair of fingers 89. As shown in Fig. 85 9 the shaft 88 is surrounded by springs 90 which are connected to the fingers 89, turnable on the shaft 88, and yieldingly maintain the fingers 89 in engagement with the edge of the right-hand former 79 as shown in Fig. 8. 90 The left-hand former 79 is similarly provided with levers 91 carrying a cross shaft 92 on which are mounted fingers 93 held in yielding engagement with the edge of the left-hand former 79 by springs 94. The only difference 95 between the fingers 89 and 93 is that the right-hand fingers 89 are longer and terminate in head portions 89a for a purpose to be shortly described with reference to the functioning 100 of these fingers.

One of the levers 87 for controlling the fingers 89 is connected by means of a rod 95 to a bell crank lever 96 pivotally mounted on a pin 97 supported from the lower side of the table 20. The other end of the bell crank lever 96 is connected to a rod 98 which, as shown in dotted lines in Fig. 1, terminates in a fork portion 99 embracing a shaft 100 extending parallel to the main shaft 10. The shaft 100 is driven in the same direction of 105 rotation and at the same speed as the shaft 10 by means of sprocket wheels 101 and a chain 102 shown in Fig. 24 so that this shaft 100 has the same function as the main driving shaft 10 in so far as the timing of the machine is concerned. As shown in Fig. 5 the shaft 100 carries a cam 103 with which a roll 104 on the yoke 99 engages so that when the high point on the cam 103 engages the roll 104 the bell crank lever 96 is turned in a clockwise direction to move the lever 87 from the position shown in Fig. 12 to the position shown in Fig. 13. The cam 103 is so timed 110 that this movement of the lever 87 occurs just after the formers 79 have wrapped the blank 1 half way around cup form 33 as shown in Fig. 12.

As previously pointed out, the fingers 89 are biased in the direction of the former 79 by the springs 90 so that as the lever 87 is 115 120 125 130

turned from the position of Fig. 12 to the position of Fig. 13 the headed ends of the fingers 89 fold the vertical right-hand side of the blank 1 smoothly around the upper right-hand quarter of the form 33 so as to cause one edge of the blank 1 to overlap the suction passages 40 opening at the top of the form 33 as shown in dotted lines. Prior to the operation of fingers 89 suction has been applied to the passages 40 by the registration of the suction nozzle 43 with the longitudinal passages 39, consequently the folded over blank is held closely to the periphery of the form 33 as soon as the fingers 89 function to fold down the blank as shown in Fig. 13. Just after the fingers 89 have folded down the blank so as to render the suction passages 40 effective in holding the blank the further turning of the cam 103 permits the rod 98 to move downwardly and return the finger lever 87 and fingers 89 to the position shown in Fig. 14 where these parts remain until the next folding operation.

Referring now again to Fig. 8 it will be seen that one of the levers 91 which control the fingers 93 has connected thereto a rod 105 pivotally connected to a lever 106 mounted on a shaft 107 supported from the underside of the table 20. The shaft 107 also carries a short lever 108 turnable with the longer lever 106 and connected to an arm 108 terminating in a fork portion 109 embracing the main shaft 10, the fork 109 carrying a roller 110 in engagement with the surface of a cam 111.

The cam 111 is so designed that as the fingers 89 reach their extreme wrapping position, a high portion 112 on the cam 111 moves the arm 108 and through it the shaft 107 to turn the lever 91 in a clockwise direction as shown in Figs. 13 and 14. In other words, the high point of the cam 111 is set behind the high point of the cam 103 so that as soon as the fingers 89 clear the top of the cup form 33 leaving the wrapped blank held by suction, the fingers 93 immediately fold over the remainder of the blank into overlapping relation with the previously folded over edge. This condition is shown in Fig. 14.

As previously pointed out, each blank 1 has had gum applied thereto along two edges as indicated at 4 in Fig. 4 and as the gummed edge is the left hand edge as presented at the wrapping station C, the overlapped edges of the blank shown in Fig. 15 are ready to be secured together upon the application of pressure. The necessary pressure is applied by the top clamp 52 which during the wrapping operations just described has remained spaced above the cup form 33 to provide enough clearance for the wrapping of the blank. However, just as the fingers 93 start to withdraw from the cup form 33 as indicated in Fig. 15, the master cam 59 which controls the top clamps 52 of all the main

turret stations is turned in a clockwise direction. The angular movement of the cam 59 is just enough to cause the shoulder 71a at the edge of the depression 71 to engage the clamp roller 58 at the station C and move the top clamp 52 towards the cup form 33 as shown in Fig. 15. In Fig. 3, the cam 59 is shown in the position which it occupies before it is turned as described above for operating the clamp roller 58 at station C.

The yielding pressure of the top clamp 52 caused by the compression of the spring 62 is sufficient to tightly seal the longitudinal seam of the cup sleeve and as soon as the fingers 93 are withdrawn from the position shown in Fig. 15, the cup form 33 is ready to be moved to the next turret station D. As the cup sleeve is moved from station to station as will be hereinafter described it is obvious from a consideration of Fig. 1 that the cam 59 will cause the top clamp 52 to hold the seam of the cup in close engagement until the station Q is reached for the first cup transfer. However before proceeding with a detailed description of the operations on the cup sleeve at the stations E to K inclusive, the details of the mechanism for feeding and positioning the cup blanks at the folding station and for delivering a bottom disk 9 at the station C will first be described.

Blank feeding mechanism

As previously pointed out with reference to Fig. 3 the stack of blanks 1 are subjected to the action of a vertically reciprocating picker 2 which may be driven in any suitable manner in timed relation with the main shaft 10 so that it makes one complete up and down movement for each revolution of the shaft 10 as shown in Fig. 16. Prior to its downward movement, the lower edge of the picker 2 is engaged by a gumming roll 113 having a reciprocating movement in a horizontal plane to and from a source of gum supply preferably a roll 114 immersed in gum. Since these parts form no part of the present invention and other means may be employed for gumming the blanks it is not believed necessary to go into a more detailed description thereof.

As the picker 2 completes its downward stroke it applies gum to two edges of the topmost blank 1 as shown in Fig. 4 so that the blank 1 is carried by the picker 2, on its upward stroke, into engagement with the stripper plate 3. This plate 3 is of the usual type employed in envelope machines and holds the ungummed portion of the blank by suction as the picker 2 continues on its upward stroke. As a gummed blank 1 is delivered to and left on the stripper plate 3 the horizontally movable carriage 5 is projected under the blank as shown in Fig. 17.

As shown in Fig. 18 the carriage 5 is adapted to have a reciprocatory movement

imparted thereto between the rails 6 by means of a lever 115 connected to the carriage 5 by a link 116. The lever 115 has an oscillatory movement imparted thereto by means of an eccentric 117 mounted on the main shaft 10 and connected to the lever 115 by a rod 118. The carriage 5 carries three equally spaced dogs 119 and the amplitude of movement of the carriage 5 for each revolution of the drive shaft 10 is substantially equal to the distance between two dogs 119, see Fig. 2.

As the carriage 5 completes its movement to the right as shown in Fig. 2 the right-hand dog 119 is positioned just beyond the edge of the blank held by the stripper 3 so that when carriage 5 starts its movement from right to left in Fig. 2 the edge of the blank 1 fits under the dog 119 and the blank 1 is carried on the rails 6 to the station A. As the blank 1 reaches this first station it lifts a pivotally mounted stop 120 shown in Fig. 18 until the rear edge of the blank passes under the end of the stop 120, whereupon the stop resumes its original position. The end of the stop 120 projects above the rails 6 so that when the carriage 5 starts on its return movement from left to right, the blank engaging the stop 120, does not return with the carriage 5 and the right-hand dog 119 is ready to take a fresh blank from the stripper 3. At the station A, the stationary blank 1 may be operated upon by a suitable embossing device, 121, if desired, as indicated in Fig. 2.

When the next revolution of the drive shaft 10 causes the carriage 5 to make another movement from right to left a middle dog 119a moves the blank on the rails 6 to a second station B where it is held by a clamp 120 as previously described. On the third revolution of the shaft 10 following the removal of the blank in question a third dog 119b moves the blank 1 to the wrapping station C for the performance of the wrapping operations which have been previously described in detail. It being of considerable importance that the blank 1 be properly positioned before being acted upon by the clamp 50 and the formers 79 shown in Fig. 7, a stop plate 122 and gauging finger 123 are provided at the station C on opposite sides of the axis of the cup form 33, as best shown in Fig. 18. The stop 122 provides a beveled edge 124 which accurately positions the extreme left-hand corner of the blank 1 while the opposite edge of the blank is still resting on the outside rails 6. In order that the cup may be symmetrical about the axis of folding 60 as viewed in plan in Fig. 17 the pivoted gauging finger 123 is provided to insure that the blank will properly engage the stop 122. As shown in Fig. 18, the finger 123 is pivotally mounted on a pin 125 which also carries a short arm 126 turnable with the finger 123.

The arm 126 is connected to a rod 127 which is forked at 128 to embrace the shaft 10. The forked portion 128 carries a roller 129 bearing on the surface of a cam 130 which is so formed that the gauging finger 123 is moved to the 70 position in full lines in Fig. 18 following the delivery of the blank 1 at the station C by the carriage 5, in which position the blank 1 is centered with respect to the cup form 33, as shown in Fig. 17.

As previously pointed out the carriage 5 derives its reciprocatory movement from the main shaft 10 through the eccentric 117 and this eccentric is so mounted with respect to the crank arm of the Geneva motion for driving the main turret that the carriage 5 will be moved from right to left to deliver a blank at station C just as the main turret is turned to position an empty cup form 33 at the wrapping station C. At this moment a formed bottom disk 9 punched from the web 8 is positioned at the wrapping station C so that it will be included within the cup sleeve whose formation has been previously described and the mechanism for forming the disks 9 will now be described.

Bottom disk mechanism

As best shown in Figs. 1 and 19 the front end of the drive shaft 10 is provided with a bevel gear 131 in mesh with a similar gear 132 carried at the lower end of a vertical shaft 133 rotatably supported within bearings 134 and 135. The lower bearing 134 is carried by a bracket 136 secured to a frame member 12 while the upper bearing 135 is carried by an arm 137 forming part of a pedestal 138 extending upwardly from the table 20. Since the bevel gears 131 and 132 are identical, the vertical shaft 133 may be considered as a part of the main driving shaft in so far as it controls the timing of the mechanism for punching and forming cup bottoms 9 from the web 8.

As shown in Fig. 2 a suitable roll of web material 8 is mounted at one side of the vertical shaft 133 on a spindle 139, the roll being adapted to deliver the web 8 in a vertical plane to a feed roll 140 mounted on a vertical axis. An intermittent rotative movement is imparted to the feed roll 140 in any suitable manner and for purposes of illustration we have shown this movement being derived from oscillatory lever 141 with a yoke portion 142 embracing the shaft 133. A suitable cam 143 on shaft 133 co-operating with a roll 144 on yoke 142 imparts to the lever 141 a complete oscillation for each revolution of the shaft 133 which oscillatory movement is imparted to a pawl arm 145. The arm 145 carries a pivotally mounted pawl 146 which is adapted to co-operate with the teeth on a ratchet wheel 147 mounted on the same shaft 148 which carries the pawl arm 145. A gear 149 is also mounted on the shaft 148 and is 130

in mesh with a gear 150 for driving the feed roll 140.

As best shown in Fig. 20 the shaft of the roll 140 carries a second gear 151 which is in mesh with a gear 152 for driving a second feed roll 153. As shown in Fig. 2 the feed roll 153 is carried by bracket 154 pivotally mounted, the end of which is connected to a spring 155 which serves to turn the bracket 154 about its pivot and hold the roll 153 in engagement with the feed roll 140. Thus each revolution of the main shaft 10 and with it the vertical shaft 133, is adapted to cause the oscillating lever 141 to turn the feed rolls 140 and 153 and so feed a predetermined length of the web 8 to the cup bottom forming and feeding mechanism which will now be described.

As best shown in Fig. 19 the feed rolls 140 and 153 are adapted to project the web 8 into a space between a pair of punch plates 156 and 157. These plates are carried by the pedestal 138 and provide alined central openings 156a and 157a of somewhat less diameter than the width of the web 8. The opening 157a in the plate 157 communicates with a slot 158 wide enough to admit the web 8 which is thus held along its edges between the plates 156 and 157.

The pedestal 138 provides a bearing for a cutter sleeve 159, one end of the sleeve 159 projecting beyond the pedestal 138 where it is connected to upper and lower eccentric disks 160 by pins 161. The eccentric disks 160 are mounted on a collar 162 keyed to the vertical shaft 133 so that rotation of the shaft 133 imparts a reciprocatory movement to the cutter sleeve 159.

The inner end of the sleeve 159 carries a cutter 163 which is in the form of a ring and provides a cylindrical cutting edge 164 that is adapted to fit inside the openings 157a and 156a in the plates 157 and 156. The length of the stroke of the cutter sleeve 159 is such that for one complete revolution of the shaft 133 the cutting edge 164 is adapted to move from the full line position shown in Fig. 19 to the position shown in dotted line within the opening 156a in the plate 156. When this occurs, a flat disk 9 is severed from the web 8 and is left in the position shown in dotted line when the sleeve 159 returns to its original position for the beginning of another stroke.

A plunger 165 is movable within the cutter sleeve 159, the projecting end of the plunger 165 being slotted to receive an eccentric disk 166 also carried by the eccentric collar 162. It will be evident from Fig. 19 that the eccentric disks 160 and 166 are so timed that the central plunger 165 will follow the cutting movement of the sleeve 159. The length of the stroke of the plunger 165 is such that the end of the plunger will pick up the punched disk 9 where it has been left in the opening

156a and carry it into an opening 167a provided in a plate 167 mounted in front of the cutter plate 156. The opening 167a is smaller in diameter than the alined openings 156a and 157a and the plunger 165 is of such diameter that it will readily pass into the opening 167a.

Therefore, as the plunger 165 carries the disk 9 into the opening 167a, the edges of the disk will be bent around the end of the plunger 165 to impart a cupped form to the disk. The plunger 165 provides a number of end openings leading from an axial passage 165a connected to a pressure source herein-after referred to. The plunger 165 is moved by the eccentric 166 far enough to carry the cupped disk 9 beyond the opening 167a into engagement with an opposed plunger 168 yieldable within a casing 169 secured to the plate 167. The plunger 168 yields against a spring 168a to receive the cupped disk 9, thereby further forming the disk by the opposed pressures of the plungers 165 and 168. As the plunger 165 withdraws, pressure through the passage 165a clears it, so that the plunger 168 alone acts on the disk 9 to push it beyond the edge of the casing 169 into a position just below the end of a vertical plunger 170, as indicated in dotted lines in Fig. 7. The plunger 170 is of substantially the same thickness as the cupped disk 9 and is slidably mounted within a guide 170a secured to the plate 167.

The vertical plunger 170 is adapted to have a reciprocatory movement imparted thereto within the guide 170a by means of a rod 171 and one way of imparting movement to the rod 171 is shown in Fig. 25. The upper end of the rod 171 is connected to the end of a lever 172 freely turnable on a shaft 173 and carrying between its ends a roller 174. This roller 174 is held in engagement with the surface of a cam 175 by means of a spring 176, the cam 175 being mounted on a shaft 177 that is supported by a vertical bracket 192 and is driven in unison with the main shaft 10. The end of the counter shaft 177 is shown in Fig. 1 and the rotation of the main shaft 10 is imparted thereto by means of a chain 178 passing around sprocket wheels 179 on the shaft 177 and on a shaft 180 which extends through the inner sleeve 63 of the main turret 7. As shown in Fig. 5 the other end of the shaft 180 carries a sprocket 181 that is connected to a sprocket wheel 182 on the main shaft 10 by means of a chain 183.

Thus the shaft 177 is driven in unison with the main shaft 10 and the plunger 170 has imparted thereto a complete reciprocatory movement for each revolution of the main shaft. The cam 175 on the shaft 177 is so timed that the plunger 170 starts its downward movement just after a cupped disk 9 has been delivered below the plunger 170 by

the horizontal plunger 168. As the plunger 170 moves downwardly its curved end portion, see Fig. 25, engages the cupped disk and positions it above the edge of the blank 1 which has just been delivered to the wrapping 5 station C as previously described.

As a disk 9 is delivered above the blank 1 by the plunger 170, it is immediately positioned on a suction head 184 the diameter of 10 which is such as to just fit within the cupped portion of the disk 9. The suction head 184 is carried at the end of a plunger 185 slideable within a bearing 186 carried by the pedestal 138. The plunger 185 provides a longitudinal 15 passage 187 which extends through the head 184 and is connected to a suitable source of suction by a pipe 188. This suction is always effective while the machine is operating so that as soon as a bottom disk 9 is delivered 20 by the plunger 170, the disk is immediately positioned on the end of the suction head 184.

The other end of the plunger 185 carries a yoke 189 with a roller 190 bearing on an eccentric disk 191 mounted on the shaft 133. 25 The eccentric disk 191 is so timed that the suction head 184 carrying a bottom disk 9 is moved towards the cup form 33 just prior to the beginning of the wrapping operations on the blank 1. The final position of the cupped 30 disk 9, during the wrapping operation, is shown in dotted lines in Fig. 19, the head 37 carried by the cup form 33 being at that time held retracted against the form 33. Thus the bottom disk 9 is held stationary at a point 35 intermediate of the long edges of the blank 1 while the latter is being wrapped about the cup form 33, as previously described in detail with reference to Figs. 10 to 15 inclusive. Therefore, when the suction head 184 with- 40 draws to its original position, the bottom disk 9 is held positioned within the cup sleeve in engagement with head 37 by reason of the fact that the cup sleeve is smaller in diameter beyond the head 37.

The position of the bottom disk 9 within the wrapped sleeve of the blank 1 is shown in 45 Fig. 21 which also shows the top clamp 52 firmly holding the seam of the cup following the completion of the wrapping operations. The head 37 of the cup form 33 is also shown 50 as being held against the smaller end of the form 33 by the spring 38 so that the bottom disk 9 is spaced an appreciable distance from the annular band of gum 4 extending around the inner surface of the cup sleeve. The central portion of Fig. 21 may, therefore, be considered as showing the condition of affairs at the wrapping station C following the completion of the wrapping operations and the 55 downward movement of the clamp 52 due to the rotation of the cam 59 which controls the movement of the top clamps 52. As previously pointed out, this movement of the cam 59 takes place at the end of the cycle of wrap- 60 ping operations and also at the termina- 65

of the interval during which the main turret 7 is stationary. Immediately after the cam 59 has functioned to cause the clamping of the cup seam, the turret 7 is turned to move the partially completed cup from station C 70 to station D. At this station no work is performed on the cup so that for the next complete revolution of the drive shaft 10 all the parts remain as shown in the central portion of Fig. 21. However, as the turret 7 is again 75 turned to move the partially completed cup from the station D to the station E, instrumentalities for sizing and positioning the bottom disk come into operation as shown in 80 Figs. 21 and 22.

Cup sizing mechanism

Before proceeding with a detailed description of the sizing mechanism reference will be had to Fig. 1 which shows the bracket 192 extending upwardly from the table 20 in front of the turret 7 and spaced therefrom as shown in plan in Fig. 2. The bracket 192 provides a flange 193 around its edge with which registers a similar flange 194 provided on a cover plate 195 secured to the bracket 192 by bolts 196. This construction is shown in section in Fig. 21 which also shows a space between the engaged flanges 193 and 194 which space is occupied by the trains of gearing shown in 90 Fig. 26 for driving the several cup spinning and expanding devices which will be hereinafter described.

Still referring to Fig. 21, a shaft 197 is 95 slidably mounted within a bushing 198 extending between the bracket 192 and the cover plate 195. The end of the shaft 197 extending beyond the bracket 192 carries a sizing sleeve 199 the inner surface of which is frusto conical with substantially the same taper as 100 the cup form 33 with which the shaft 197 is co-axial. The other end of the shaft 197 carries a collar 200 having a groove 201 for receiving pins 202 extending inwardly from the arms of a yoke 203 shown in Figs. 1 and 105 29. The yoke 203 forms part of an arm carried on a shaft 204 which is supported on a bracket 204a and carries a second forwardly extending arm 205 pivotally connected to a link 206 extending in the direction of the vertical shaft 133. As best shown in Fig. 2 the link 206 terminates in a forked portion 207 embracing the shaft 133 and adapted to have an oscillatory movement imparted thereto by means of a cam 208. With this 110 connection, each revolution of the main shaft 10 is adapted to impart a complete reciprocatory movement to the shaft 197 carrying the sizing sleeve 199.

When a partially completed cup is moved 115 from the idle station D to the sizing station E the parts of the sizing mechanism occupy the positions shown in Fig. 21. As soon as the turret 7 comes to rest, however, the shaft 197 moves the sizing sleeve 199 from the po- 120 125

sition shown in Fig. 21 to the position shown in Fig. 22, a slot 199a in the sleeve 199 permitting the movement of the sleeve 199 without interference from the top clamp 52. As the shaft 197 is moved to bring the sleeve 199 into sizing position, a plunger 209 engages the rear end of the spindle 36 carrying the head 37 in engagement with the bottom disk 9. This plunger is slidably mounted in lugs 210 and is surrounded by a spring 211 which bears against a collar 212 carried by plunger 209 to normally hold it retracted from the end of the spindle 36. After the turret has come to rest and the shaft 197 starts to bring the sleeve 199 to the sizing position, a lever 213 engages the end of the plunger 209 and moves it into engagement with the end of the spindle 36. The lever 213 is mounted on a shaft 214 as shown in Fig. 5 which shaft carries an arm 215 having a roll 216 at its end in engagement with a cam 217 carried by the main drive shaft 10. When the plunger 209 is moved to its extreme left-hand position as shown in Fig. 22, the head 37 carries the bottom disk 9 towards the base of the cup sleeve until the bottom disk 9 is positioned in register with the annular band of gum 4 near the end of the sleeve. During this movement of the bottom disk 9 the cup sleeve is held firmly in shape by the inclosing surface of the sizing sleeve 199 so that in moving from the position of Fig. 21 to the position of Fig. 22, the flange of the bottom disk 9 undergoes a change in form. When the bottom disk 9 is first loosely positioned within the wrapped sleeve its flange 9a flares outwardly as shown in Fig. 23a but as the disk 9 is pushed against the converging sides of the cup sleeve, the flange 9a first loses its outward flare as shown in Fig. 23b and finally has imparted thereto an inward flare corresponding to the taper of the cup sleeve, as shown in Fig. 23c. The bottom disk 9 then occupies the position shown in Fig. 22 wherein it is held in position by the extended head 37. The sizing of the cup is now complete and as the drive shaft 10 starts another revolution the sized cup is moved from station E to station F for the first spinning operation.

As this movement occurs the end of the plunger 36 engages a curved bar 218 mounted in back of the turret 7 as shown in Fig. 24 with its curvature corresponding to the path traversed by the ends of the spindles 36. This bar 218 extends from just beyond station E over stations F to K inclusive and insures that the head 37 will be held stationary to prevent any shifting of the bottom disk 9 away from the base of the cup sleeve during the cup bottom spinning operations which will now be described.

Cup bottom spinning mechanism

As previously pointed out the shaft 177 is driven in unison with the main shaft 10 and this shaft 177 is journaled between the bracket 192 and its cover plate 195 as shown in Fig. 27. The shaft 177 carries a gear 219 between the bracket and its plate, which gear 219 is in mesh with a gear 220 having the same number of teeth so as to drive its shaft 221 at the same speed as shaft 177 although in the opposite direction as shown in Fig. 26. The gear 220 is in turn in mesh with an idler gear 220a which is in mesh with a train of gears 220b to 220f inclusive for driving shafts 222, 223 and 224 at the same speed and in the same direction as the shaft 221. Other gears 220g, 220h and 220i are driven from gear 219 for driving shafts 225 and 226 at the same speed and in the same direction as the shafts 221 to 224 inclusive. With this gearing, the bracket 192 carries six parallel shafts 221 to 226 inclusive all rotating at the same speed and in the same direction, each shaft being mounted in the same manner as shaft 224 shown in Fig. 28 which shaft 224 is rotatable in bosses 227 provided by the bracket 192 and its cover 195.

The shaft 224 is hollow to receive a spring 228 which extends therethrough and is anchored at one end to a pin 229 carried by the bracket boss 227. The other end of the spring 228 is connected to a rock arm 230 pivoted on a shaft 231, the spring 228 tending to hold the roller 232 carried by the arm 230 in engagement with the face of a cam 233 carried by the shaft 224. The other end of the rock arm 230 terminates in a yoke portion 230a providing inwardly extending pins 234 which are received in a groove 235 on a collar 236, see Fig. 29. The collar 236 is carried at the end of a shaft 237 slidable and rotatable in bushings 237a provided by the brackets 192 and 195 so that rotation of the shaft 224 is adapted to impart a reciprocatory movement to the shaft 237 through the cam 233 acting on the roller 232.

The shaft 237 carries a gear 238 connected thereto by means of a key 239 received in a slot 240 provided in the gear 238, so that axial movement of the shaft 237 by the rocker arm 230 is permitted while the gear 238 is driving the shaft 237. As shown in Fig. 26, the gear 238 is in mesh with a gear 241 provided on a shaft 242 extending rearwardly through the bracket 192 and coupled to the shaft 243 of an electric motor 244 shown in Fig. 2. Three other shafts 245, 246 and 173 extending parallel to the shaft 237 are adapted to be driven in the same direction and at the same speed as the shaft 237 by means of a train of idle gears 247 and driving gears 248 all the same size, the first one 247 of which is in mesh with the gear 238.

The end of the shaft 237 extending beyond the bracket 192 carries a spinner head 249 which comprises a disk carrying a number of spaced ribs 250 as shown in Fig. 25. When the sized cup arrives at station F from station E as previously described, the spinner head 249 is held retracted by the spring 228 so that the ribs 250 are separated from the edge of the cup sleeve 1. However as the shaft 224 is driven by the main shaft, the high part of the cam 233 causes the rocker arm 230 to move the shaft 237 axially in the direction of the cup sleeve 1 thereby causing the revolving spinner head 249 to engage the smaller rim of the cup. As this occurs the ribs 250 spin over the edge of the cup sleeve as shown in Fig. 30, the bottom disk 9 of the cup at this time being firmly held by the plunger head 37 as previously described. The shaft 237 is thereupon withdrawn by the action of the spring 228 as the cam roller 232 passes off the high point of the cam 233 and the turret moves the partially spun cup from station F to station G.

As best shown in Fig. 25 the shaft 245 which is in alignment with station G carries a spinner head 251 similar to the spinner head 249. The mechanism for axially moving this shaft 245 is similar to the mechanism for moving the shaft 237 with the exception that the operating collar 252 on the shaft 245 is nearer the head 251 than collar 236 is to head 249. Consequently the spinner head 251 is moved further in the direction of the cup form 33 thereby further spinning over the flange 1a around the bottom of the cup as shown in Fig. 31. When this occurs the shaft 245 is retracted and the turret is turned to move the partially spun cup from station G to station H.

The third spinner shaft 246 carries a spinner head 253 similar to the head 249 and the mechanism for axially moving this shaft 246 is similar to that for moving the shaft 237 with the exception that the collar 254 on the shaft 246 is nearer the head 253 than collar 252 is to head 251. Consequently the shaft 246 moves the spinner head 253 still farther towards the cup sleeve 1 so as to turn over the flange 1a to the point where it nearly touches the flange 9a of the bottom disk 9 as shown in Fig. 32. Upon completion of the third spinning at station H the turret 7 is again turned to move the spun cup from station H to station I.

The shaft 173 which supports the lever 172 as previously described, also carries an ironer head 255 which provides a flange 255a of slightly less diameter than the inside diameter of the flange 9a on the bottom disk 9 of the cup at station I. The shaft 173 is axially movable in the same manner as shaft 237 with the exception that the collar 256 on the shaft 173 is nearer to head 255 than the collar 254 is to head 253. As a result, rotation

of the shaft 221 causes the ironer head 255 to move towards the cup form 33 far enough to engage the spun over flange 1a and turn it over into parallel relation with the flange 9a on the bottom disk 9 to form a water tight seam at the bottom of the cup. This is shown very clearly in Fig. 33, after which operation the head 255 is withdrawn to permit the cup to be moved from station I to station J for expanding the base of the cup.

Bottom expanding mechanism

In order to expand the spun over flange 1a of the cup sleeve 1 into close relation with the flange 9a of the bottom disk 9, two expanding devices are provided at stations J and K respectively. These expanding devices are mounted on shafts 257 and 258 respectively, slidably mounted in the bracket 192 in substantially the same manner as the shaft 237. The shafts 257 and 258 do not carry driving gears but are adapted to be moved axially by cams 259 and 260 carried on the shafts 225 and 226 respectively, as shown in Figs. 1 and 25.

As best shown in Figs. 34, 35 and 36 the shaft 257 and also the shaft 258 carries at its end a head 261 secured against axial movement on the shaft 257 by means of a set screw 262, the shaft 257 being free to turn within the head 261 without imparting movement to the head. The head 261 projects beyond the end of the shaft 257 and provides an annular flange portion 263, the inner surface 264 of which has the same taper as the base of the cup sleeve 1. The head 261 also provides a number of radial slots 265 in each of which is pivotally mounted a lever 266 on a pin 267. The levers 266 extend forwardly inside the flange 263, the end of the levers 266 normally resting on flattened surfaces 268 provided at the end of the shaft 257, as shown in Fig. 34.

The ends of the levers 266 are yieldingly maintained in engagement with the flat shaft surfaces 268 by means of spring fingers 269 shown in Fig. 35, but it is obvious from Fig. 34 that should the shaft 257 be turned through a small angle, the ridges 270 between the flat surfaces 268 will engage the levers 266 and cause them to simultaneously turn about their axes in the direction of the surrounding flange 263. Means for imparting an angular movement to the shaft 257 is shown in Fig. 1 wherein a crank arm 271 carried by the shaft 257 beyond its shifting collar 272 is connected by means of a rod 273 providing a fork embracing a cam 274 mounted on the counter shaft 100.

The cam 274 is so timed with relation to the cam 259 which moves the shaft 257 axially, that the head 261 is first moved towards the cup at station J to cause the bottom of the cup to be received within the tapered surface 264 with the ends of the contracted levers 266 inside of the flange 1a of the cup

sleeve 1. As the flange 263 reaches this position, the thrust rod 273 turns the shaft 257 through an angle equal to substantially one-half the angular displacement of the levers 266, thereby causing the ridges 270 on the end of the shaft 257 to simultaneously move all the levers 267 outwardly and compress the engaged flanges 1a and 9a of the cup outwardly against the surrounding rigid wall of the flange 263. When the shaft 257 is turned to operate the levers 266, the head 261 is prevented from turning with the shaft 257 by reason of the fact that the tapered recess 264 is then engaged by the base of the cup 1, thereby imposing a frictional resistance to turning of the head portion 263. Further rotation of the drive shaft 10 causes the levers 266 to be collapsed and the head 261 to be withdrawn from the cup, after which the turret 7 is moved to shift the cup from station J to station K.

As previously pointed out the expanding device at station K mounted on shaft 258 is substantially the same in construction as the expanding device just described with reference to shaft 257. The only difference resides in the fact that the levers 266a on the shaft 258 are displaced angularly on the shaft 258 with respect to the levers 266 on the shaft 257 as shown in Fig. 25. Consequently, when the flange 263a on the shaft 258 is advanced to receive the bottom of the cup and the levers 266a are expanded by turning the shaft 258, the flange 1a of the cup bottom is engaged by the ends of the levers 266 at points angularly displaced from the points at which the levers 266 engaged and expanded the flange 1a. The shaft 258 is turned with the shaft 257 by a crank arm 271a connected to rod 273. After the cup has been acted upon by the second set of expanders, it is completed in so far as the formation of the sleeve and bottom is concerned and when the cup is moved to station L following the withdrawal of the expanding device on shaft 258 no operations are performed thereon.

At station L the nearly completed cup is permitted to dry while its seam is held tight by the top clamp 52 and it is obvious that the period allowed for drying of the gum is determined by the number of drying stations provided on the turret 7 between the last expanding station K and the first transfer station Q. As shown in Figs. 1 and 3 we have provided five drying stations designated L, M, N, O and P respectively at each of which the nearly completed cup is held stationary during the period that the various operations previously described are performed on the cup blanks 1 as they successively arrive at the folding station C and proceed from station to station until they leave the station K.

It is obvious from Fig. 3 that all during the period that the cup is traveling from station D to station P the cam 59 holds the top

clamp 52 fast against the seam of the wrapped cup, but as the cup whose progress we have been following reaches station Q the above described angular movement of the cam 59 permits the top clamp roller 58 to enter the cam depression 71 whereupon the clamp 52 is released and the cup is ready to be transferred to the secondary turret 11 for the performance of the final operation of spinning the rim of the cup and for delivering the completed cup to a suitable receiving device as will now be described.

The secondary turret

Referring now to Figs. 37 and 38, the table 20 provides a pedestal 275 at one side of the main turret 7, which pedestal provides a bearing portion 276 for a hollow shaft 277 with which turns the secondary turret 11 indicated diagrammatically in Fig. 3. The inner end of the shaft 277 carries a gear 278 in mesh with the gear teeth 24 on the outer periphery of the main turret 7. The shaft 277 also carries a three armed spider 279, the arms 280 of which are identical and each carry a hollow conical holder 281 the inner surface of which is adapted to receive a partly completed cup. The ratio between the teeth on gear 278 and the teeth 24 on the main turret is such that for each movement of the main turret 7 through the angle between adjacent stations, the secondary turret 11 is turned through 120° which is the angle between the center lines of the spider arms 280. As best shown in Fig. 38 one cup holder 281 is always in axial alignment with the cup form 33 at the transfer station Q and the mechanism for effecting the transfer of a cup from the form 33 to a holder 281 in alignment therewith is shown in Fig. 39.

As previously pointed out, the spindle 36 inside the cup form 33 is hollow and as the main turret 7 comes to the rest at the station Q the passage 36a extending through the spindle 36 comes into alignment with a passage 282 extending longitudinally through a plunger 283, the end of which is reduced to form a nozzle 284 spaced from the back side of the main turret flange 7a. The plunger 283 is slidably mounted in a bracket 285 extending upwardly from the table 20 and the projecting portion of the plunger provides a slot 286 for receiving the end of an upwardly extending arm 287. As shown in Fig. 38 the hub 288 of the arm 287 is mounted on the cross shaft 214 supported by bearing brackets 289 and 290 projecting from the underside of table 20, the shaft 214 being operated by the cam 217 on the main shaft 10, see Fig. 5. At the time the turret 7 is turned to bring a cup form 33 into position at the transfer station Q, the plunger 283 is held retracted by the arm 287 against the pull of a spring 292, but as soon as the arm 287 starts to move in a clockwise direc-

tion under the action of the cam 217, the spring 292 advances the plunger 283 in the direction of the cup form 33. This movement of the plunger 283 is transmitted to the spindle 36 carrying the head 37 so that the cup is positively separated from the form 33 when the head 37 forces the bottom disk 9, away from the form 33.

As this occurs, a passage 293 extending diametrically through the plunger 283 comes into register with a passage 294 extending through the bracket 285 which passage 294 is connected to a suitable source of air pressure which will be hereinafter referred to. When air pressure is thus admitted to the alined passages 282 and 36a, a blast of air is delivered against the bottom disk 9 of the cup then loose on the form 33 which moves it into the alined cup holder 281 on the secondary turret 11. If desired, the source of pressure connected to the passage 294 can be so controlled as to cause separate blasts of air to be delivered to the passage 36a thereby insuring the complete transfer of a cup into the holder 281 in case the first blast has not carried the cup all the way. After the transfer has taken place and before the turret 7 has turned to bring another cup to the transfer station Q, the arm 287 withdraws the plunger 283 thereby shutting off the air pressure in the passage 282 as the passage 293 moves out of register with passage 294.

As the main turret 7 is turned again following the transfer of a cup into the holder 281 at the station Q, the secondary turret 11 is turned through an angle of 120° to bring the holder 281 containing the cup to the position designated as station S in Fig. 3, at which station it is desired to carry out the operation of spinning the open rim of the cup to present a smooth surface. As the secondary turret 11 is turned to bring one of its arms 280 into the spinning position, the whole turret is locked against rotative movement about its axis during the spinning operation by means of a vertically movable plunger 295 extending upwardly through the table 20 the upper end of which provides a notch for receiving a roller 296 mounted on a pin 297 carried at the end of the turret arm 280, see Fig. 40. The plunger 295 is slidable within a guide 298 carried by the table 20 and is connected at its lower end by a pin 299 and link 300 to a lever 301 carried on a shaft 301a below the table 20, see Fig. 37. As shown in Fig. 1 the shaft 301a and the lever 301 are adapted to be turned by means of a second lever 302 carrying a roll in engagement with the surface of a cam 303 mounted on the main drive shaft 10. The cam 303 is so designed that the plunger 295 is in its lowermost position when the secondary turret 11 is turned to swing a turret arm 280 into position at the spinning station S, whereupon the plunger 295 is moved upwardly to cause the roller

296 to be received in its notch, thereby effectively holding the secondary turret against any rotative movement about its axis during the rim spinning operation which will now be described.

70

Rim spinning mechanism

As best shown in Fig. 40 a sleeve 304 is slidably mounted in a bearing 305 carried by the table 20, the axis of the sleeve 304 coinciding with the axis of the cup holder 281 at the spinning station S. The sleeve 304 extends beyond the bearing 305 and carries an annular bearing 306 for rotatably supporting a spinner ring 307. The ring 307 provides peripheral gear teeth 308 which are in mesh with the teeth of a gear 309 rotatably supported on a short shaft 309a carried by the table 20. The teeth of gear 309 are considerably wider than the teeth 308 on the spinner ring 307 so that the teeth will remain in mesh when the spinner ring 307 is moved axially with the sleeve 304.

75

80

85

As shown in Fig. 37 the gear 309 is in mesh with the teeth of a segmental gear 310 providing a hub 311 freely rotatable on a shaft 312 supported below the table 20 by brackets 313. The shaft 312 is adapted to have an oscillatory movement imparted thereto by means of an arm 314 connected to a rod 315 terminating in a yoke 315a embracing the drive shaft 10, see Fig. 38. The yoke 315a carries a roller 316 in engagement with a cam 317 on the shaft 10 whereby each revolution of the shaft 10 turns the shaft 312 through one complete oscillation. This movement is imparted to the segmental gear 310 by means of a crank 318 carried by the shaft 312 and connected to the gear 310 by a pin 319, so that for each revolution of the drive shaft 10 the spinner ring 307 is turned through a predetermined angle. The cam 317 is so designed that for a portion of a revolution of the main shaft 10 the spinner ring 307 remains stationary for a purpose to be 105 hereinafter described.

90

100

105

110

115

120

125

130

A plunger 320 is received within the spinner sleeve 304 and carries at its end a tapered head 321 normally held extended beyond the ring 307 by a spring 321a. The head 321 has the same taper as the upper portion of the cup sleeve 1, as positioned within the cup holder 281. The sleeve 304 is adapted to be moved within the bearing 305 by means of a pair of rods 322 pivotally connected to the opposite sides of the sleeve 304 by pins 323 and pivotally connected at their other ends to a lever arm 324. As shown in Fig. 37 the lever arm 324 is carried on the cross shaft 214 which also carries the arm 287 and when the shaft 214 is turned by the cam on the main shaft 10 the sleeve 304 is moved in the direction of the cup holder 281. During the first part of this movement the head 321 moves with the spinner ring 307, that is until the head 321 enters

within the cup holder 281. After that the spring 321a yields to permit the spinner ring 307 to telescope slightly on the head 321, as shown in Fig. 40a. The sleeve plunger 320 is prevented from rotating with the ring 307 by a key 325 received in a slot 325a provided in the sleeve 304.

As the spinner ring 307 is carried toward the rim of the cup by the sleeve 304, the cup rim enters a small groove 307a in the end of the spinner ring 307 and the rotation of the spinner ring 307 but not the head 321 has the effect of spinning over the rim of the cup to provide a rounded lip as indicated at 1b. During this operation, the wall of the cup just below the rim is rigidly supported by the surface of the head 321 so that no strain is imposed upon the cup during the spinning operation. In other words, that portion of the cup wall immediately below where the rim spinning is taking place is actually clamped between the opposed surfaces of the head 321 and the outer portion of the cup holder 281, since the head 321 has substantially the same taper as the holder 281. After the spinning operation, the spinning ring 307 is positively held against longitudinal movement by means of a latch lever 326 that is disposed behind the top of the lever arm 324 which carries the rods 322 for moving the spinner ring sleeve 304. The lever 326 is pivoted at 326a and is connected by link 327 to an arm 328 mounted on a shaft 214a extending through the shaft 214. As best shown in Fig. 38 the inner shaft 214a extends underneath the table 20 to a point above the counter-shaft 100 where it is provided with an arm 329 adapted to receive an oscillatory movement from a cam 330 mounted on the shaft 100 operating through a link 330a as shown in Fig. 5. The cam 330 is so timed that the lock lever 326 is moved downward just after the crank arm 324 moves the ring 307 to the rim spinning position, the lock lever 326 remaining in this position until after a rim crimping ring 331 has operated. The lever 326 is shown in Fig. 37 as about to engage the ends of the rods 322 to positively lock the ring 307 against longitudinal movement while the crimping ring 331 is operating, which movement might otherwise occur due to lost motion in the mechanism operating the plunger 320. After the crimping has taken place the lock lever 326 is moved upwardly to permit the withdrawal of the sleeve 304.

As the spinning is completed the spinner ring 307 comes to rest and is locked as previously described, whereupon the crimping ring 331 comes into operation. As best shown in Fig. 40a this crimping ring 331 is slidable on the outer periphery of the cup holder 281 and is carried by a pair of rods 332 extending through ears 281a provided on the holder 281. The rods 332 provide shoulders 333 and these shoulders are normally held against the ears

281a by means of springs 334 which as shown in Fig. 37 are each anchored at one end to the cup holder 281 and connected at the other end to the crimping ring 331. The rods 332 extend rearwardly through the turret arm 280 on either side of the axis of the holder 281 and terminate a short distance away from the ends of a pair of aligned plungers 335. As best shown in Fig. 40, the plungers 335 are slidably mounted in bosses 336 provided by a bracket 337 on the table 20, each plunger 335 being held retracted away from its rod 332 by means of a spring 338 surrounding the plunger 335 between a head 339 on the plunger and its boss 336. The plungers 335 are adapted to be simultaneously moved into engagement with the rods 332 by means of a pair of fingers 340 mounted on a shaft 341 also carried by the bracket 337. The shaft 341 carries an arm 342 projecting downwardly through the table 20 and pivotally connected to one end of a rod 343. The other end of the rod 343 is pivotally connected to an arm 344 mounted on a shaft 345 extending underneath the table 20 to a point above the main shaft 10. The shaft 345 is turnable with another arm 346 the lower end of which carries a roller 347 in engagement with a cam 348 on the shaft 10.

As the shaft 10 completes a revolution and is about to turn the secondary turret 7 through another step, the cam 348, through the linkage just described, imparts a turning movement to the shaft 341 thereby causing the fingers 340 to thrust the plungers 335 into engagement with the rods 332. The rods 332, in turn, carry the crimping ring 331 toward the then stationary spinning ring 307 thereby causing the rounded edge of the ring 331 to jam the spun lip 1b compactly within the groove 307a of the spinning rim 307 which is then positively locked by lever 326. The crimping ring 331 is thereupon withdrawn by the springs 334 as the fingers 340 are turned in a clockwise direction away from the rods 335 and at the same time, retraction of the spinning ring 307 is caused by the lever arm 324. Just as the ring 307 and the head 321 are withdrawn from the completed cup, a blast of air is admitted to the plunger 320 through a passage 349 which is in register with a pipe 350 leading into the bearing 305 from a suitable pressure source, as shown in Fig. 43 the control of which will be hereinafter described. This blast of air impinges upon the bottom 9 of the cup and insures there will be no tendency for the cup to stick to the head 321. The completed cup then having been properly positioned in the holder 281 following the spinning and crimping operations, all is in readiness for the next turn of the secondary turret 11 to bring the completed cup to the second transfer position designated station T, where the completed cup is cleared from the machine

and stacked for packing, or any other desired use.

Final delivery of cup

The final clearing of a completed cup is shown in Fig. 41 in which the section taken along the inclined section line 41—41 of Fig. 38 is considered as having been swung about the axis of the turret 11 into a vertical plane. As the arm 280 carrying the completed cup is turned from station S to station T, an inclined surface 351 on a cam plate 352 supported from the table 20 by a bracket 352a engages the end of a plunger 353 slidable within the pin 297 which projects rearwardly from the cup holder 281 in axial alignment therewith. The plunger 353 provides a head 354 which is normally held in engagement with a bottom plate 355 provided in the base of the holder 281, by means of a spring 356 shown in Fig. 40a. When the plunger 353 is pushed inwardly by the inclined surface 351 on the stationary cam 352, the head 354 pushes the bottom plate 355 forwardly, thereby exerting a pressure directly on the bottom rim of the cup and loosening the same from the sides of the holder 281.

This movement of the bottom plate 355 is completed just as the arm 280 of the turret 11 comes into position at station T and the inward movement of the plunger 353 also permits a jet of air to be delivered directly against the bottom of the cup just after it has been freed. For this purpose, the head 354 provides a right angled passage 358 in which registers with a radial passage 358 in the arm 280 and this passage 358 in turn is in communication with the interior of the bearing 276 through a passage 359. The outside of the shaft 277 provides a groove 361 which is adapted to be connected to a source of pressure by means of a pipe 360, see Fig. 42, the shaft groove 361 communicating with the axial passage 359 and radial port 358 in the delivery position.

When the air blast is delivered through the opening 357 against the bottom of a finished cup as just described, the force of the air clears the cup from its holder 281 and delivers it open end first between a number of guide bars 363 which are spaced apart just far enough to receive and guide the finished cup substantially in a straight line. The guide bars 363 are carried by a ring 364 mounted on a bracket 365 extending upwardly from the table 20 as shown in Fig. 37. A number of finished cups are shown as already having been delivered to the guide bars 363, the cups arranging themselves in nesting relation so as to build up a stack as successive cups are delivered, open end first, from the cup holder 281 at station T. The guide bars 363 hold the completed cups so that a stack thereof can be readily removed as desired. Having described the complete

formation of a cup through the various stages, on both the main and secondary turrets, various details of the control of our machine will next be considered.

70

Control of the machine

As pointed out at various places in the foregoing description, a source of pressure is employed to bring about the first cup transfer from the main turret 7 to the secondary turret, to clear a cup from the rim spinning tools and to bring about the final delivery of a finished cup to the stack of completed cups. Suitable means for controlling this source of pressure is shown in Figs. 42 and 43, wherein a reservoir 366 is shown as being supplied from a constant source of pressure by means of a pipe 367. The reservoir 366 provides a number of spaced ports 368 which are adapted to be controlled by slide valves 369, 370, 371 co-operating with cams 372, 373 and 374 respectively mounted on the countershaft 100. The valve 369 controls the connection of the pipe 350 to the reservoir 366, the pipe 350 as previously described leading to the bearing 305 where it connects with the interior of the plunger 320. The cam 372 controlling the valve 369 is so designed that the port 368 is open to the pipe 350 for a very short period just before the turret 11 is about to be turned, the rim spinning operation having been completed at that time.

The valve 370 controls the admission of air to a pipe 375 leading to the passage 294 in the bracket 285 which communicates with the passage 293 in the plunger 283 for delivering the blast which completes the first transfer from the main turret 7 to the secondary turret 11. The cam 373 which controls the valve 370 is so designed that the pipe 375 is connected to the reservoir 366 after the cup form head 37 has freed the cup, the nozzle 284 then being in register with the passage 36a extending through the head 37. The valve 371 controls admission of air to the pipe 360 leading to the groove 361 on the hollow shaft 277 of the secondary turret 11. The cam 374 controlling the valve 371 is so designed as to admit pressure to the pipe 360 just as the turret 11 is locked in position by the plunger 295. A fourth valve 460 controlled by cam 461 admits pressure to passage 165a in plunger 165.

Referring now to Figs. 44 and 45, there is shown diagrammatically an arrangement for controlling the operation of all of the mechanism previously described. As shown in Fig. 5 the main drive shaft 10 is adapted to be connected to the power pulley 14 by the clutch member 15, and the cylinder 19 for moving the clutch member 15 is shown in detail in Fig. 44. The base 19a of the cylinder 19 provides a port 376 leading to a valve chamber 377 within which a slide valve 378 is adapted to be moved by means of a rod 130

379. The rod 379 is pivotally connected to an arm 380 carried by a shaft 381 mounted on the table 20 as shown in Fig. 24. The shaft 381 is provided with one or more handles 382 by means of which the shaft 381 can be turned to move the valve 378 in the chamber 377, and in Fig. 44 the handle 382 is shown in such position that the main shaft 10 is unclutched from its driving pulley 14.
- 10 The valve chamber 377 provides a port 383 which receives a pipe 384 permanently connected to a source of pressure not shown. A port 385 is provided diametrically opposite the port 383 but with the valve 378 in raised position the ports 383 and 385 are not connected. The port 385 is connected by a pipe 386 to a port 387 near the base of chamber 377, which port 387 is in alignment with the passage 376 leading to the cylinder 19. The pipe 367 leading from the pressure reservoir 366 also connects with the port 385 so that with the parts in the position shown in Fig. 44 no pressure is applied anywhere on the machine.
- 25 The valve 378 provides a pair of cross ports 388 and 389 so spaced that when the handle 382 is turned in a clockwise direction into the position shown in Fig. 45 the resulting downward movement of the valve 378 brings the cross port 388 into register with the cylinder ports 383 and 385. This same movement brings the lower cross port 389 into register with the port 387 and the passage 376 leading to the cylinder 19 so that air under pressure from the pipe 384 is admitted to the base of the cylinder 19 below the piston 18 as indicated by arrows. When this occurs, upward movement of the piston rod 17 throws the clutch member 15 into engagement with
- 30 the corresponding clutching surface of the power pulley 14 thereby applying power to the shaft 10 to perform the cycle of operations previously described. It will also be seen that when the upper cross port 388 regis-
- 35 ters with the port 385, air under pressure is admitted to the reservoir 366 through pipe 367 so that operation of the counter shaft 100 causes pressure to be supplied for carrying out the first cup transfer, the stripping of
- 40 the cup after rim spinning and the final transfer, all as previously described.
- 45 When the handle 382 is turned into the position shown in Fig. 45 to start the shaft 10, a switch arm 390 carried thereby establishes electrical connections to set in operation the previously described motor 244 for driving the various spinning tools. As merely illustrative of one way in which this
- 50 may be accomplished, the switch arm 390 carries a contact plate 391 which is adapted to bridge normally separated contacts 392 which provide a gap in the circuit of the motor 244, as shown in Fig. 44. When the handle 382 is moved to the starting position
- 55 the contact plate 391 connects the contacts

392 thereby completing the circuit of motor 244.

The contact arm 390 carries a second bridging plate 393 which is adapted to complete the circuit between two spaced stationary contacts 394 which are included in the circuit of a motor 395. This motor 395 drives a suction pump 396 and as shown in Figs. 1 and 42 the suction side of pump 396 is connected to the pipe 188 which supplies suction to the plunger 185 for holding and positioning cup bottoms. The pump 396 is also connected to the suction passage 46 in the plunger 44 by a pipe 46a which applies suction to the cup form 33 at the initiation of the wrapping of a cup blank 1 about the cup form 33, see Fig. 5.

The control shaft 381 also carries a knock-off arm 397 which is moved into close proximity to a tripping plunger 398 when the handle 382 is turned to connect the shaft 10 to the power pulley 14. The plunger 398 is surrounded by a spring 399 which tends to urge the plunger head 400 in the direction of the knock-off arm 397, but normally the plunger 398 is held retracted with the spring 399 compressed by means of a trip 401. The trip 401 is here shown as being electrically controlled by means of a solenoid 402 surrounding the trip, a spring 403 holding the beveled end of the trip 401 in a notch 404 provided in the plunger 398. One terminal of the solenoid 402 is connected to a suitable source of electrical energy indicated at 405, but the solenoid 402 is normally in a de-energized condition owing to the fact that the circuit from the other terminal of the solenoid 402 is open between the solenoid 402 and the source 405. There may be one or more breaks provided in the circuit of the solenoid 402 and in the present embodiment we have provided for the control of the solenoid circuit by means of detecting devices adapted to stop the machine, first in the event that a partially completed cup fails to be removed from the main turret at the transfer station Q and secondly, in the event that a completed cup fails to be cleared from the secondary turret 11 at the final transfer station T. The detecting devices are shown in Figs. 46 to 49 inclusive, and will now be described.

In Fig. 46 a cup form 33 is shown in transverse section as being provided with a slot 406, so that when there is no cup on the cup form 33 a detecting finger 407 may enter into and bottom in the slot 406. The finger 407 is pivoted at 408 and carries a contact 409 which is normally held away from a stationary contact 410 by means of a spring 411 carried by a bracket 412 which supports the finger 407. The movable contact member 409 is connected to one terminal of the solenoid 402 by means of a conductor 413 while the stationary contact 410 is connected to one side of the source 130

405, so that when the contacts 409 and 410 are separated there is a gap in the circuit of the solenoid 402.

As indicated in Fig. 3, the detector finger 407 is located at the station R on the main turret 7, at which station there never should be a cup on the cup form 33 when the machine is operating properly. Therefore, under all normal conditions of operation the contacts 409 and 410 are held separated and the solenoid 402 will remain deenergized as long as the detector finger 407 is pressed in the slot 406 of any one of the sixteen cup forms 33 by the spring 411.

In Fig. 47 the cup form 33 is shown as having a cup sleeve 1 thereon, it being assumed that for some reason this cup has failed to be transferred to the secondary turret 11 at the preceding station Q. As the cup form 33 with the cup thereon swings toward the detector finger 407 and comes to rest at station R, the finger 407 is prevented from entering the slot 406 and consequently is forced downwardly in a clockwise direction about its pivot 408 to bring contact 409 into engagement with the stationary contact 410. When this occurs the circuit of the solenoid 402 is completed and the resulting energization of the solenoid 402 withdraws the end of the trip 401 from the notch 404 in the plunger 398. The compressed spring 399 is then free to quickly force the plunger 398 upwardly, thereby causing the head 400 to engage the knock-off arm 307 and turn the shaft 381 in a counter-clockwise direction. This movement of the shaft 381 returns the arm 382 to its inoperative position shown in Fig. 44, thereby raising the valve 378 to cut off pressure from the cylinder 19. When this occurs, air is exhausted from the cylinder 19 through the open port 376 thereby withdrawing the clutching member 15 from the pulley 14 and stopping the shaft 10. Simultaneously with this movement, the switch arm 390 breaks the circuit of both motors 244 and 395 so that the spinning tools cease to rotate and suction is cut off from the machine. Upward movement of the valve 378 also cuts off pressure from the reservoir 366 so that functioning of the detecting finger 407 immediately brings the machine to a completely inoperative condition.

As shown in Fig. 48 a second detector finger 414 is mounted so that it may engage the rim of a cup holder 281 as the secondary turret 11 moves from the second transfer station T over to the first transfer station Q. The finger 414 is pivoted at 415 and is normally urged in the direction of the cup holder 281 by means of a spring 416 compressed between the finger 414 and a bracket 417. The finger 414 carries a contact 418 which is normally out of engagement with a contact 419 carried by the bracket 417 when the end of the finger 414 is in engagement with the rim of an empty

cup holder 281. The contact 418 is connected to one terminal of the solenoid 402 by a conductor 420 while the stationary contact 419 is permanently connected to the source 405.

In normal operation of the machine, the rim of the cup holder 281 is clear as the holder is moved from station T back to station Q so that the contacts 418 and 419 remain separated. However should a completed cup fail to be ejected from the holder 281, the finger 414 will engage the rim 1b of the cup as the turret 11 swings, as shown in Fig. 49. When this occurs the finger 414 is turned far enough to close the contacts 418 and 419 thereby energizing the solenoid 402 and operating the trip 398 to release the knock-off arm 397 as previously described. Thus the machine is immediately brought to rest should a completed cup fail to be transferred at the last station T. Following functioning of the trip plunger 398 as described above, it may be manually reset by pushing down on it until the end of the trip 401 is forced into the notch 404 by the spring 403, where it remains until the solenoid 402 is again energized.

From the foregoing it is apparent that by our invention we have provided a machine, that once set in motion, will automatically produce completed stiff drinking cups without requiring any manual operations whatsoever on the part of the machine attendant. When running, our machine functions to simultaneously perform a large number of separate operations on cups in different stages of completion, so that at all times a considerable number of partially completed cups are in the process of drying at the idle stations on the main turret, prior to the performance of the final rim spinning operation on the secondary turret. As a result, the machine is capable of a high rate of production and is obviously able to produce cups much faster than a machine in which several successive operations are performed on a cup at a single station. In other words, our machine is particularly characterized by the fact that the duration of a single operation at any station is reduced to a minimum, thereby resulting in a corresponding rapid delivery rate for the finished cups.

With respect to the foregoing description of the operations performed on a given blank in its progress from station to station on the main turret, it should be borne in mind that during the normal operation of the machine there is always plenty of time for the seams along the gummed portions of the cup to dry thoroughly before the finished cup is handled. This is a very important feature and is made possible of attainment by breaking up the total number of operations necessary to form a cup into a number of simultaneously performed separate operations of brief duration with a pause between each operation. Thus the flat blank 1, upon being gummed

is maintained in a flat condition during three revolutions of the drive shaft which gives the exposed gum a chance to dry slightly and reach a condition of tackiness most favorable for adhesion to a dry surface. Then when the flat blank is folded into the form of a sleeve at the station C, the longitudinal seam of the sleeve is held tightly clamped during the next fourteen revolutions of the drive shaft 10, thereby insuring that this longitudinal seam will be quite dry by the time the seam clamp 52 is released as the cup reaches station Q. The clamping of this longitudinal seam for a considerable period is of great importance, for otherwise the natural tendency for the wrapped blank to unroll itself would cause the edges at the longitudinal seam to separate should pressure along the seam be released before the gum was thoroughly dry.

With regard to the annular seam between the flange 9a of the bottom disk 9 and the wall of the cup, it is apparent that when once this seam is made by the final positioning of the bottom disk 9 at the sizing station E, the bottom disk is positively maintained in this position at the succeeding spinning and expanding stations F to K inclusive. While the cup sleeve is being operated upon at these stations the head 37 of the cup form is held extended by the curved bar 218 in which position of the head 37 the bottom disk 9 can not move away from the position in which it is gummed. Furthermore, the division of the bottom spinning into three operations at stations F, G and H, respectively, insures that the gum in contact with the bottom flange 9a around the bottom seam will have a chance to dry during three revolutions of the drive shaft before the flanged bottom portion 1a of the cup sleeve is finally ironed over into engagement with the bottom flange 2a at station I. It is quite apparent from a consideration of Fig. 33 that the turned back flange 1a will serve to lock the bottom flange 9a into position to provide a water-tight seam and that the locking engagement between these flanges will be still further increased by the operation of the expanding devices at the stations J and K respectively which tend to pinch the flange 9a between the gummed wall of the sleeve and the turned over sleeve flange 1a.

After a cup has left the second expanding station K, the cup form head 37 which has previously been positively held in engagement with the bottom 9 is withdrawn so that while a cup is being moved through drying stations L to P inclusive for a period of five revolutions of the drive shaft 10, the annular bottom seam has a further chance to dry since this seam is then more fully exposed to the air by the withdrawal of the head 37. Therefore, by the time a cup is transferred from the main turret 7 to the secondary turret 11 at the station Q both the longitudinal seam

and the annular bottom seam will have thoroughly dried, so that the pressure of the head 37 and the blasts of air directed against the bottom 9 at the stations Q, S and T will have no tendency whatsoever to loosen the bottom 9. It is obvious that the spinning of the rim 1b on the nearly completed cup at the station S will in no way weaken the longitudinal seam of the sleeve since the upper portion of the cup wall is securely clamped between the cup holder 281 and the head 321 when the rim spinning takes place.

It is obvious that our machine is susceptible of modifications in the manner of performing the various operations on the cups without departing from the general principles of forming a cup in accordance with our invention. The essential principle of our machine resides in the simultaneous performance of a comparatively large number of related operations at different stations on the machine, whereby a maximum delivery rate is obtained, and it is obvious that all these various operations can be performed in proper timed relation by other means than the utilization of a large number of cams driven either directly, or indirectly, from a single power shaft. For example, it would be perfectly possible to impart reciprocatory movement to the several spinning and expanding tools by electro-magnetic or pneumatic means, without in any way departing from the spirit and scope of our invention. It is also possible to vary the driving relation between the main turret 7 and the secondary turret 11, one such modification being shown in Figs. 50, 51 and 52 which will now be described.

Referring now to Fig. 50 there is shown a modified arrangement for driving the main turret 7 through the secondary turret 11 which is driven from the main shaft 10 through the Geneva motion. In this modified arrangement, the main turret 7 is mounted as before on the table 20 which also carries bearings 421 for supporting a countershaft 422 just above the table 20. As shown in Fig. 52 one end of the shaft 422 carries a gear 423 driven from a gear 424 on the drive shaft 10 through a belt 425 extending behind the table 20.

The same end of shaft 422 carries a crank 426 that is adapted to be received in any one of four slots 427 provided in a head 428 carried by a shaft 429. The shaft 429 is mounted in vertical alignment with and parallel to the shaft 422 and since the gears 423 and 424 have the same number of teeth, it is obvious that one revolution of the shaft 10 will cause the shaft 429 to be turned through one-quarter of a revolution.

The shaft 429 carries a four armed spider 430 similar in many respects to the spider of the turret 11 with the main exception that four cup holders 281 are provided thereon instead of three. The rotation of the turret

shaft 429 is adapted to be imparted to the main turret 7 by means of a gear 431 meshing with the gear teeth on the turret 7 and the relation between the gearing is such that when 5 the shaft 429 is turned through one quarter of a revolution, the turret 7 will be turned through the angle between the center lines of adjacent cup forms 33. Consequently each time the secondary turret spider 430 is turned, 10 one of its cup holders 281 will come into axial alignment with one of the cup forms 33, just as described with reference to the turrets 7 and 11.

The table 20 provides a bearing bracket 432 which supports a plunger 433 carrying a rim spinner ring 434. The rim spinner ring 434 carries a gear 435 in mesh with a wide gear 436 on the shaft 422 so that the spinner ring 434 is constantly driven. The plunger 433 carries a roll 437 in engagement with a cam 438 mounted on a shaft 439 supported above the shaft 422 in bearings 440. The shaft 439 is driven at the same speed as the shaft 422 by means of helical gears 441 so that the plunger 25 433 is adapted to operate the rim spinner ring 434 after a cup has been positioned in alignment with the spinner 434 by lower right hand cup holder 281 in Fig. 50.

The shaft 439 also carries a cam 442 for operating a bell crank lever 443 pivoted at 444 to move a plunger 445 into operative position at the first transfer station, the plunger 445 serving to loosen a cup and to control a blast of air for effecting the transfer of a cup from 30 a cup form 33 to a cup holder 281 on the secondary turret, as previously described. As shown in Fig. 52, the plunger 445 operates in a bearing bracket 446 extending above the bracket 432 which carries the spinner ring 35 plunger 433, the end of plunger 445 being adapted to engage the end of the spindle 36 on the cup form 33.

The cross shaft 439 also carries a third cam 447 on which bears a roll 448 carried by 45 a plunger 449 slideable in a bearing bracket 450 similar to bracket 432. The plunger 449 carries a flanged head 451 and the cam 447 moves the head 451 within a cup holder 281 prior to the operation of its crimping ring 50 331 so as to support the spun over rim of a cup as operated on at the previous spinning station. The operating rods 332 of the crimping ring 331 are adapted to be engaged by studs 452 on a cross head 453 carried by a 55 plunger 454 movable in a bearing 455. The plunger 454 is connected to a lever 456 pivoted at 457 the lower end of which carries a roll 458 bearing on a cam 459 carried by shaft 422.

60 With this modified structure of the secondary turret, the operations of rim spinning and crimping are carried out at different stations, thereby giving a longer period for carrying out each operation. This results in 65 a more perfectly formed cup rim. Driving

the main turret 7 from the secondary turret also results in a lessened tendency for the secondary turret to overrun. The main turret 7 is always locked at the end of each turning movement by the engagement of the cup formers 79 with the cup form 33 at the wrapping station C, so there is no tendency for the main turret 7 to overrun.

We claim:

1. The improvement in the art of making 75 cups which consists in simultaneously delivering a flat blank and a circular disk to a rigid non-rotatable cup form and then wrapping said blank into a sleeve around said form while maintaining said disk at one end of said cup form to provide a bottom for the cup sleeve.

2. The improvement in the art of making 80 cups which consists in simultaneously delivering a flat blank and a circular disk to a rigid non-rotatable cup form and then wrapping said blank into a tapered sleeve around said form while maintaining said disk loosely within said sleeve.

3. The improvement in the art of making 85 cups which consists in simultaneously delivering a flat blank and a circular disk to a rigid non-rotatable cup form with said blank and said disk at right angles to each other and then wrapping said blank into a sleeve about said form to surround said disk and provide a closure for the sleeve.

4. The improvement in the art of making 90 cups which consists in simultaneously delivering a flat gummed blank and a flanged circular disk to a rigid cup form and then wrapping said blank about said form to loosely surround said disk with the gum on said blank adapted to contact with the flange of 95 said disk.

5. The improvement in the art of making 100 cups which consists in simultaneously delivering a flat gummed blank and a flanged circular disk to a rigid cup form and then wrapping said blank about said form to loosely surround said disk with an annular band of 105 gum on said blank spaced from the flange of said disk.

6. The improvement in the art of making 110 cups which consists in simultaneously delivering to a rigid cup form a flat blank gummed along two edges and a flanged disk and then wrapping said blank about said form into a sleeve surrounding said disk, with the gum on one edge of said blank adapted to engage 115 the flange on said disk and with the gum on the other edge of said blank engaging the opposite ungummed edge to provide a longitudinal seam for the cup sleeve.

7. The improvement in the art of making 120 cups which consists in simultaneously delivering to a rigid non-rotatable cup form a flat blank gummed along two edges and a flanged disk, next wrapping said blank around said form into a sleeve loosely sur- 125

rounding said disk with one gummed edge of said blank engaging the opposite edge of the blank and then clamping the engaged edges of the blank together on said cup form 16 to form the longitudinal seam of the sleeve.

8. The improvement in the art of making cups which consists in simultaneously delivering to a rigid cup form a flat blank gummed along two edges and a flanged disk, next

10 wrapping said blank around said form into a sleeve surrounding said disk with one gummed edge of said blank engaging the opposite edge of the blank then clamping the engaged edges of the blank together to 15 form the longitudinal seam of the cup and finally moving said disk in said sleeve to bring its flange into engagement with an annular band of gum near one end of said sleeve, before said longitudinal seam has dried.

9. The improvement in the art of making drinking cups which consists in positioning at a given point a flat blank gummed parallel to one edge and a round disk providing a flange, then wrapping said blank into a tapered sleeve providing an annular band of gum near one end, said sleeve loosely surrounding said disk with the flange of said disk spaced from said annular band of gum 30 at the smaller end of said sleeve and finally moving said disk toward the smaller end of said sleeve to bring its flange into wiping engagement with said annular band of gum.

10. The improvement in the art of making 35 drinking cups which consists in positioning at a given point a flat blank gummed parallel to one edge and a round disk providing a flange, then wrapping said blank into a sleeve loosely surrounding said disk with said gum 40 in an annular band near one end of said sleeve, then moving said disk in said sleeve to bring its flange into engagement with said band of gum and finally spinning over the end of said sleeve into interlocking relation 45 with the flange of said disk before the gum in contact with the disk flange has dried.

11. The improvement in the art of making 50 drinking cups which consists in positioning at a given point a flat blank gummed parallel to one edge and a round disk providing a flange, then wrapping said blank into a sleeve loosely surrounding said disk with said gum 55 in an annular band near one end of said sleeve, then moving said disk in said sleeve to bring its flange into engagement with said band of gum, then spinning over the end of said sleeve into interlocking relation with the flange on said disk and finally applying internal radial pressure to expand the engaged 60 spun over sleeve and bottom disk flange and lock the bottom seam before the gum on said disk flange has dried.

12. The improvement in the art of making 65 drinking cups which consist in positioning a flat blank and a circular disk in symmetri-

cal relation with respect to the axis of a non-rotatable form, wrapping said blank around said form to form a sleeve concentric about said axis and loosely enclosing said disk and subsequently performing other operations on 70 said sleeve and said bottom disk and transferring a completed cup to a stack of cups, with the axis of the cup sleeve always parallel to the original axis of wrapping.

13. The improvement in the art of making 75 drinking cups which consists in positioning a flat blank and a circular disk in symmetrical relation with respect to the axis of a non-rotatable form, wrapping said blank around said form to form a sleeve concentric 80 about said axis and loosely enclosing said disk and subsequently performing spinning operations on both ends of said cup sleeve with the axis of said cup sleeve always parallel to the original axis of wrapping.

14. The improvement in the art of making 85 drinking cups which consists in positioning a flat blank and a circular bottom dish in symmetrical relation with respect to the axis of a non-rotatable form, wrapping said blank 90 around said form to form a sleeve concentric about said axis and loosely enclosing said disk and next spinning the closed end of said cup to interlock the enclosed bottom dish, with the axis of the cup sleeve parallel to the original axis of wrapping.

15. The improvement in the art of making 95 drinking cups which consists in positioning a flat blank and a circular bottom disk in symmetrical relation with respect to the axis of a non-rotatable form, wrapping said blank 100 around said form to loosely enclose said bottom disk and form a sleeve concentric about said axis, next spinning the closed end of said cup sleeve to interlock said bottom and then spinning the open rim of said cup sleeve, with the axis of said cup sleeve in parallel relation with the original axis of wrapping.

16. The improvement in the art of making 110 a series of round drinking cups from flat blanks and round bottom disks which consists in wrapping a blank loosely around a bottom disk to form a cup at one point, spinning over one end of the cup sleeve to lock the bottom disk on a previously wrapped cup at another point and expanding the turned over bottom on another previously formed cup at a third point.

17. The improvement in the art of making 120 a series of round drinking cups from flat blanks and round bottom disks which consists in wrapping a blank loosely around a bottom disk to form a cup at one point and simultaneously performing the operations of positioning a bottom disk within the sleeve, spinning over the base of the sleeve to lock the bottom disk and expanding the spun over sleeve portion within the bottom disk on previously formed cups at other points.

18. The improvement in the art of making 130

5 a series of round drinking cups from flat blanks and round bottom disks which consists in wrapping a blank loosely around a bottom disk to form a cup at one point, simultaneously positioning a bottom disk within a cup sleeve, and spinning over one end of a cup sleeve into locking engagement with its bottom disk on other previously formed cups at different points, by supporting the cup 10 sleeves around their rims, and at the same time shifting another partially completed cup along the direction of its axis to support it with its rim free.

15 19. The improvement in the art of making a series of round drinking cups from flat blanks and round bottom disks which consists in simultaneously performing the operations of wrapping a blank into a sleeve to loosely encircle a bottom disk, positioning a 20 bottom disk within a sleeve, and spinning over the bottom of a sleeve to lock its bottom disk, at different points on different cup sleeves, and shifting a partially completed cup along its axis to support it with its rim 25 free and simultaneously spinning the open rim of another base supported cup at another point.

30 20. The improvement in the art of making round drinking cups from flat blanks and round bottom disks which consists in wrapping a cup blank into the form of a sleeve around a loosely positioned bottom disk, then positioning the bottom disk within an annular band of gum inside the sleeve and in positively maintaining the bottom disk in engagement with the gum, then performing the subsequent operations of bottom spinning and locking the bottom disk on the same cup at different stations.

35 40 21. In a machine for forming round cups from flat blanks and round disks, a rotatable turret, means for imparting intermittent angular movement in one direction to said turret and means cooperating with said turret 45 at different stations thereon for wrapping a cup blank into a sleeve around a bottom disk, for progressively spinning the bottom of the sleeve into locking engagement with a bottom disk by a series of successively performed operations, for expanding the bottom 50 of the cup and for clearing the partially completed cup from the turret in an axial direction.

55 22. In a machine for forming round drinking cups from flat blanks and round disks, a rotatable turret providing rigid non-rotatable cup forms, means for imparting intermittent angular movement in one direction to said turret, means cooperating with the turret for wrapping a cup blank around a rigid form on said turret with a bottom disk loosely positioned within the cup sleeve and further means for positively positioning the bottom disk within the cup sleeve while said 60 sleeve is clamped to the cup form.

65 23. In a machine for forming round drinking cups from flat blanks and round disks, a rotatable turret providing rigid non-rotatable cup forms, means for imparting intermittent angular movement in one direction to 70 said turret, means cooperating with the turret for wrapping a blank around a rigid form on said turret to provide a tapered sleeve with a bottom disk loosely included therein, means for positively positioning said bottom disk within the cup sleeve while said sleeve is clamped to the cup form and further means for spinning the smaller end of the cup sleeve into locking engagement with the bottom disk while the cup sleeve is 75 clamped on said form.

80 24. In a machine for forming round drinking cups from flat blanks and round disks, a rotatable turret providing rigid non-rotatable cup forms, means for imparting intermittent angular movement in one direction to 85 said turret, means for wrapping a blank around a rigid cup form to provide a tapered sleeve in which a bottom disk is loosely received, means for positively positioning a bottom disk within the smaller end of the sleeve while the sleeve is clamped to the form, means for spinning over the smaller end of the sleeve into locking engagement with the bottom disk and further means for 90 expanding the spun over sleeve portion within the bottom disk.

95 25. In a machine for forming round drinking cups, the combination with means for individually feeding flat blanks, means for punching flat circular disks from a continuous web and a stationary cup form, of means for simultaneously positioning a blank below said cup form and a disk at right angles thereto at the end of the form and further means for wrapping said blank around said form to provide a sleeve enclosing said disk.

100 26. In a machine for forming round drinking cups, the combination with means for individually feeding flat blanks, means for punching flat circular disks from a continuous web and a stationary tapered cup form, of means for positioning a blank in a horizontal plane below said cup form, means for positioning a disk in a vertical plane in engagement with the end of said cup form and means for wrapping said blank around said cup form to provide a tapered sleeve loosely surrounding said disk.

105 110 27. In a machine for forming round drinking cups, the combination with means for individually feeding flat blanks, means for punching flat circular disks from a continuous web and a stationary cup form, of means for positioning a blank in a horizontal plane below said cup form, means for positioning a disk in a vertical plane in engagement with the end of said cup form, means for clamping said blank in engagement with the lower 115 surface of said cup form and means for wrap- 120 125 130

ping first one side of said blank and then the other around said cup form to loosely surround said disk and bring the edges of the blank into engagement to provide a longitudinal seam for the cup sleeve.

28. In a machine for forming round drinking cups, the combination with means for individually feeding flat blanks, means for punching flat circular disks from a continuous web and a stationary cup form having suction openings therein, of means for gumming one edge of a blank, means for positioning a blank in a horizontal plane below said cup form, means for clamping said blank 10 at its middle portion to the lower surface of said cup form, means for folding one side of said blank around said cup form to a point where it is held by suction applied to the openings in said cup form and further means for 20 wrapping the other side of said blank around said form to bring its gummed edge into engagement with the other edge of said blank to provide a longitudinal seam for the cup sleeve.

29. In a machine for forming round drinking cups, the combination with means for individually feeding flat blanks, means for punching flat circular disks from a continuous web and a stationary cup form having 30 suction openings therein, of means for gumming one edge of a blank, means for clamping the middle portion of the blank to the underside of said cup form, means for wrapping one side of said blank around said form to bring its edge into register with the suction openings in the cup form to hold the blank, means operating after the return of the first 35 wrapping means for wrapping the other side of said blank around said form to bring its 40 gummed edge into engagement with the suction held edge and means for clamping the engaged edges together along the longitudinal seam thus formed after the return of the second wrapping means.

30. In a machine for forming round drinking cups, the combination with a cup form carrying a blank wrapped into the form of a tapered sleeve with a circular disk loosely positioned at the smaller end of said cup form 50 and means for clamping the engaged edges of the blank along said form, of means for moving said disk within said cup sleeve to engage it with an annular band of gum extending around the inner surface of said cup sleeve.

31. In a machine for forming round drinking cups, the combination with a frusto conical cup form carrying a blank wrapped about it with the edges of the blank clamped in engagement on the cup form and a circular disk included within the tapered cup sleeve with a peripheral flange loosely engaging cups, the combination with frusto conical moving said disk within said cup sleeve to conform its flange to the taper of the cup 60 sleeve and bring said flange into engagement 65

with an annular band of gum extending around the inner surface of the cup sleeve.

32. In a machine for forming round drinking cups, the combination with a cup form carrying a sleeve wrapped thereon with a flanged bottom disk held in locking engagement with said sleeve by a turned over portion of said sleeve, of a plurality of sets of jaws for radially expanding the turned over sleeve portion into close engagement with the surrounding flange of said bottom disk at different points angularly displaced around the periphery of said flange.

33. In a machine for forming round drinking cups, the combination with a cup form carrying a sleeve wrapped around it with a bottom disk secured in the sleeve at one end of said cup form and a recessed cup holder in axial alignment with said cup form, of means for separating said cup from said cup form by pressure applied to its bottom disk and for transferring said cup, bottom first, into said cup holder.

34. A machine of the class described, the combination with a rotatable turret carrying a plurality of peripherally spaced cup forms on parallel axes each adapted to support a cup around its rim and a second rotatable turret providing a plurality of recessed cup holders on parallel axes, of means for imparting a step-by-step rotative movement to said turrets with a cup form on one turret in axial alignment with a cup holder on the other turret at the end of each step and means for transferring a cup from a cup form into a cup holder by pressure applied to the cup bottom.

35. In a machine of the class described, the combination with a recessed cup holder for receiving a tapered cup and supporting it around its closed bottom, means for engaging the open rim of said cup extending beyond said holder for spinning it over to form a bead and further means operating from the opposite direction and after said spinning means for compressing the previously spun bead.

36. In a machine for making cups each consisting of a cup sleeve and bottom, the combination with means for supporting a cup around its open rim, means for supporting a cup around its closed end and means for transferring a cup from one supporting means to the other, of means for automatically stopping the machine upon the failure of a cup to be transferred.

37. In a machine for making cups each consisting of a cup sleeve and bottom, the combination with means for supporting a cup around its open rim, means for supporting a cup around its closed end and means for transferring a cup from one supporting means to the other by the application of pressure to the cup bottom of means for automatically stopping the machine upon the

failure of a bottomless cup to be transferred.

38. In a machine for making cups each consisting of a cup sleeve and bottom, the combination with means for supporting a

5 cup around its open rim, means for supporting a cup around its closed end and means for transferring a cup from one supporting means to the other, of means for automatically stopping said machine in the event of a

10 cup moving beyond its transfer position.

39. In a machine for making cups each consisting of a cup sleeve and bottom, the combination with means for supporting a cup around its open rim, means for supporting a

15 cup around its closed end and means for transferring a cup from one supporting means to the other by the application of pressure to the cup bottom, of means for automatically stopping said machine in the event

20 of a bottomless cup being moved beyond its transfer position.

40. In a machine for making cups, each consisting of a cup sleeve and a bottom, the combination with means for supporting a

25 cup around its open rim, means for supporting a cup around its closed end, means for transferring said cup from one supporting means to the other and means for ejecting said cup, open end first, from said bottom

30 supporting means, of means for automatically stopping said machine upon failure of said transfer means or of said ejecting means.

41. In a machine for making cups, each consisting of a cup sleeve and a bottom, the

35 combination with means for supporting a cup around its open rim, means for supporting a cup around its closed end, means for transferring said cup from one supporting means to the other and means for eject-

40 ing said cup, open end first, from said bottom supporting means with both of said transfer and ejecting means operating on the bottom of the cup, of means for automatically stopping said machine upon the failure

45 of a bottomless cup to be either transferred or ejected.

42. In a cup forming machine, means for wrapping a blank into a sleeve surrounding a bottom, means for spinning the open rim

50 of said sleeve, means for ejecting a spun sleeve from said machine and means for automatically stopping the operation of said machine should a bottomless cup fail to be ejected.

55 43. In a cup forming machine, means for wrapping a blank into a sleeve, means for spinning the open rim of said sleeve, means for ejecting the spun cup from the machine and means for automatically rendering said

60 rim spinning means inoperative should a spun cup fail to be ejected from said machine.

44. In a cup forming machine, means for wrapping a blank into a sleeve, means for

65 spinning the open rim of said sleeve, and

means for automatically stopping said machine upon the failure of a cup to arrive in position for being operated upon by said rim spinning means.

45. In a cup forming machine, means for 70 wrapping a blank into the form of a sleeve to include a circular bottom disk, means for spinning the open rim of said sleeve, means for preventing functioning of the rim spinning means following the formation of a sleeve without a bottom disk included therein.

46. In a machine for making cups, the combination with a source of power, a driving shaft, means for connecting said shaft to said source of power, means driven by said shaft for forming cups with bottoms therein, a source of pressure, and means for applying said pressure source for transferring a completed cup by the application of pressure to the bottom thereof, of means for automatically disconnecting said shaft from said source of power and for cutting off said cup transfer means from said source of pressure, in the event of the formation of a cup without a bottom by said machine.

47. In a machine for making cups, the combination with a source of power, a driving shaft, means for connecting said shaft to said source of power, means driven by said shaft for forming cups with bottoms therein, a source of pressure, and means for applying said pressure source for transferring a completed cup by the application of pressure to the bottom thereof, of a detecting device adapted to automatically disconnect said shaft from said source of power and to cut off said cup transfer means from said source of pressure in the event that a cup fails to be transferred.

48. In a machine for making cups, the combination with a rotatable turret for supporting cups thereon around their open ends, a second rotatable turret for supporting cups around their closed ends, means for driving said turrets in unison, a source of pressure, and means for transferring a cup from the first turret to the second turret by the application of pressure from said source, of means for automatically arresting the rotation of said turrets and for simultaneously cutting off said cup transfer means from said pressure source in the event a cup is not transferred from the first turret to the second turret.

49. In a machine for making cups, the combination with a rotatable turret for supporting cups thereon around their open ends, a second rotatable turret for supporting cups around their closed ends, means for driving said turrets in unison, a source of pressure and means for transferring a cup from the first turret to the second turret by the application of pressure from said source, of means co-operating with the first named turret for

automatically arresting movement of said turrets and for simultaneously cutting off the transfer means from said suction source in the event that a cup without a bottom fails to be transferred from the first turret to the second turret.

50. In a machine for making cups, the combination with a rotatable turret for supporting cups with bottoms around their closed ends, means for imparting intermittent rotative movement to said turret, a source of pressure, and means for ejecting completed cups from said turrets, open end first, by the application of pressure from said source to the cup bottoms, of means for co-operating with said turret for automatically arresting rotative movement thereof and for automatically cutting off said ejecting means from said pressure source in the event of the failure of a cup on said turret to be ejected.

51. In a machine for making cups, the combination with a source of power, a driving shaft, means for connecting said shaft to said source of power, means driven by said shaft for forming cups with bottoms, a source of electrical energy and a motor connected to said source for driving tools operating on said cups, of means for automatically disconnecting said shaft from said source of power and for disconnecting said motor from said electrical source in the event of the formation of a cup without a bottom.

52. In a machine for making cups, the combination with a source of power, a driving shaft, means for connecting said shaft to said source of power, means driven by said shaft for forming cups with bottoms, a source of electrical energy, and a motor connected to said electrical source for driving tools operating on said cups, a source of pressure and means for applying said pressure source for transferring a cup by the application of pressure to the bottom thereof, of means for automatically disconnecting said shaft from said power source, for disconnecting said motor from said electrical source and for cutting off said cup transfer means from said pressure source in the event that a cup fails to be transferred.

53. In a machine for making cups, the combination with a source of power, a driving shaft, means for connecting said shaft to said source of power, and means driven from said shaft for delivering blanks, one by one, to a wrapping station, for forming cup bottoms from a continuous web and for wrapping each blank in the form of a sleeve surrounding a cup bottom, of means for automatically disconnecting said shaft from said power source in the event of the formation of a cup without a bottom.

54. In a machine for making cups, the combination with a rotatably driven shaft, and means driven from said shaft for delivering blanks, one by one, to a wrapping station,

for forming cup bottoms from a continuous web and for wrapping each blank in the form of a sleeve surrounding a cup bottom, of means for automatically rendering said blank feeding, bottom forming and sleeve wrapping devices ineffective, in the event of a cup being formed without a bottom.

55. In a machine for making cups, the combination with a source of power, a driving shaft, means for connecting said shaft to said source of power, and means driven from said shaft for delivering each blank, one by one, to a wrapping station, for forming cup bottoms from a continuous web and for wrapping blanks in the form of a sleeve surrounding a cup bottom, of means operable upon the bottom of a cup for transferring a cup following the sleeve wrapping operation, and means for automatically disconnecting said shaft from said power source upon the failure of the cup transferring means to function.

56. In a machine for making cups, the combination with a rotatably driven shaft, and means driven from said shaft for delivering blanks, one by one, to a wrapping station, for forming cup bottoms from a continuous web and for wrapping each blank in the form of a sleeve surrounding a cup bottom, of pneumatic means for transferring a cup by pressure applied to its bottom, and means for automatically rendering said blank feeding, bottom forming and sleeve wrapping means ineffective upon the failure of a cup without a bottom to be transferred.

57. In a machine for making cups, the combination with a source of power, a driving shaft, means for connecting said shaft to said source of power, and means driven from said shaft for delivering each blank, one by one, to a wrapping station, for forming cup bottoms from a continuous web and for wrapping blanks in the form of a sleeve surrounding a cup bottom, of means for ejecting a completed cup from the machine, open end first, and means for automatically disconnecting said driving shaft from said power source upon the failure of a cup to be ejected.

58. In a machine for making cups, the combination with a source of power, a driving shaft, means for connecting said shaft to said source of power, and means driven from said shaft for delivering each blank, one by one, to a wrapping station, for forming cup bottoms from a continuous web and for wrapping blanks in the form of a sleeve surrounding a cup bottom, of pneumatic means for ejecting a completed cup from the machine by the application of pressure to the cup bottom, and means for automatically disconnecting said shaft from the power source upon the failure of a cup without a bottom to be ejected.

59. The improvement in the art of making drinking cups which consists in positioning a flat blank and a round disk at a non-rotata-

ble conical cup form, then wrapping said blank around said form to loosely surround said disk and finally shifting said disk into yielding engagement with the wall of the wrapped cup sleeve to provide a water-tight bottom closure for the completed cup.

60. The improvement in the art of making drinking cups which consists in positioning a flat blank and a round disk at a non-rotatable cup form, then wrapping said blank around said form into a tapered sleeve loosely surrounding said disk at its smaller end and finally projecting said disk into yielding engagement with the contracted wall at the smaller end of said sleeve to provide a water-tight closure for said sleeve.

61. The improvement in the art of making drinking cups which consists in positioning at a non-rotatable cup form a flat blank and a round disk with a compressible peripheral flange, then wrapping said blank around said form to loosely surround said disk and finally shifting said disk axially within the surrounding sleeve, with its flange in yielding engagement with the wall of said sleeve, to provide a water-tight closure for the cup.

62. The improvement in the art of making drinking cups which consists in positioning at a non-rotatable cup form a flat blank and a round disk with an outwardly flaring flange, then wrapping said blank around said form into a tapered sleeve loosely surrounding said disk and finally moving said disk toward the smaller end of said sleeve to cause its flange to take an inward flare corresponding with the taper of the cup sleeve.

63. In a machine for forming round drinking cups, the combination with a cup form carrying a blank wrapped around said form to provide a sleeve, with a flanged circular disk positioned within said cup sleeve and spaced from one end of said sleeve, of means for moving said cup form into a plurality of different positions in which that portion of the cup sleeve extending beyond the flange of the bottom disk is first progressively spun over the edge of the disk flange by a series of successively performed operations and then pressed within the flange in locking relation.

64. In a machine for forming round drinking cups, the combination with a cup form carrying a blank wrapped around said form to provide a sleeve, with a flanged circular disk positioned within said cup sleeve and spaced from one end of said sleeve, of means for moving said cup form into a plurality of different positions in which that portion of the cup sleeve extending beyond the flange of the bottom disk is first progressively spun over the edge of the disk flange by a series of successively performed operations, then pressed within the flange in locking relation and finally is expanded radially outward to force the turned-over sleeve portion into

close engagement with the surrounding flange of said bottom disk.

65. In a machine for forming round drinking cups, the combination with a cup form carrying a blank wrapped around said form to provide a sleeve, with a flanged circular disk positioned within said sleeve and spaced from one end thereof, of a series of rotating tools longitudinally movable with respect to the axis of said sleeve, said tools being adapted to progressively act on that portion of the sleeve extending beyond said bottom disk to spin said sleeve portion over the edge of said bottom disk flange and press the spun-over sleeve portion into locking relation with the flange on said bottom disk.

CERTIFICATE OF CORRECTION.

Patent No. 1,876,931.

September 13, 1932.

VINCENT E. HEYWOOD ET AL.

It is hereby certified that error appears in the printed specification of the above numbered patent requiring correction as follows: Page 24, lines 77, 104 and 117, claims 55, 57 and 58, respectively, for the words "each blank" read "blanks", lines 80, 107 and 120, for "blanks" read "each blank"; and that the said Letters Patent should be read with these corrections therein that the same may conform to the record of the case in the Patent Office.

Signed and sealed this 29th day of November, A. D. 1932.

**M. J. Moore,
Acting Commissioner of Patents.**
